POURING SPOUT CAN COVER MACHINE

John M. Hothersall, Brooklyn, N. Y., assignor to
 American Can Company, New York, N. Y., a
 corporation of New Jersey

Application November 13, 1933, Serial No. 697,826

25 Claims.

(Cl. 113—1)

The present invention relates to machines for producing can covers having hinged pouring spouts and has particular reference to apparatus embodying automatic can cover feeding, conditioning of the covers for the reception of pouring spouts which are automatically assembled with the can covers and which are hingedly secured to rivets which in turn are automatically formed from wire fed into the machine, the formed rivets being positioned in and clinched to the can covers prior to receiving the pouring spouts.

An important object of the invention is the provision of an apparatus having cooperating inter-connected devices for feeding a fibre can cover individually to a piercing station where an opening is cut in the cover wall, the cover so prepared being then provided with a staple cut off from a piece of wire and formed and assembled in the cover adjacent the opening, after which a formed metallic pouring spout is assembled to the cover within its opening and is hingedly secured to the staple.

A further object of the invention is the provision of an apparatus of the character described having a series of operating stations at which testing control devices are located and these controls insure normal, smooth flow of the elements composing the hinge spout can cover elements through the various stations so that all can covers are complete after passing through the apparatus.

An object of the invention is the provision of improved wire staple forming devices in a machine of the character described which cut a staple blank from a wire and simultaneously sharpen the ends of the cut piece so that when a staple is formed therefrom it may be easily forced in proper position through a can cover.

A further object of the invention is the provision of spout feeding and clinching devices for a pouring spout cover forming machine wherein a hinge part of a pouring spout is hingedly secured to a staple fastened in a can cover so that the spout may be hingedly moved within the cover and on the staple.

Yet another object of the invention is the provision of electric controls for wire feeding, for can cover positioning, for staple inserting and clinching and for spout assembling and hinging, so that a normal and complete operation of the feeding, positioning, inserting and clinching, assembling and hinging devices takes place only in the event that wire, cover and pouring spout are present and properly located in the machine.

The invention in one embodiment contemplates

the use of a turret for a hinged pouring spout cover apparatus which receives a formed cover and presents it successively to a piercing station where an opening is cut in the cover, to a staple inserting station where a formed staple is assembled in the cover adjacent the opening, to a spout inserting station where a formed spout is inserted into the opening and assembled with the staple, to a clinching station where the spout is hingedly secured to the staple, and finally to a discharge station where the fully formed hinged pouring spout cover is removed from the machine.

Numerous other objects and advantages of the invention will be apparent as it is better understood from the following description, which, taken in connection with the accompanying drawings, discloses a preferred embodiment thereof.

Referring to the drawings:

Figure 1 is a perspective view of an apparatus embodying the present invention;

Figs. 2 to 12, inclusive, are perspective and sectional graphic representations of the can cover parts at their different stages of formation, beginning at Fig. 2 with the cover as it looks when received in the machine and ending with the finally clinched and hinged pouring spout can cover of Fig. 12; Fig. 3 showing the cover pierced or cut out in an opening for the spout; Fig. 4 showing the inserted hinge staple adjacent the opening, and Fig. 5 showing it clinched in place; Fig. 6 indicating the alignment of the pouring spout and the cover opening with Figs. 7, 8, and 9 showing different intermediate positions relating to the inserting of the spout, and Figs. 10 and 11 showing, respectively by perspective and section, an initial clinching of the spout on the rivet which is completely clinched in the sectional view of Fig. 12;

Figs. 13 and 14 are enlarged transverse sectional views of the central part of the apparatus, these figures including, respectively, the left and right hand sides of the complete section as taken substantially along the line 13, 14 in Fig. 1;

Fig. 15 is an end elevation of the apparatus partly broken away as viewed from the pouring spout entrance end of the machine, this point of view being indicated by the dot-and-dash line 15—15 in Fig. 13;

Fig. 16 is a similar kind of elevation of the opposite or cover feed end of the machine, the point of view being indicated by the broken section line 16—16 in Fig. 14;

- Fig. 48 is a plan sectional detail taken substantially along the broken section line 48—48 in Fig. 45;
- Fig. 49 is a transverse section viewed along the line 49—49 in Fig. 45;
- Fig. 50 is an enlarged sectional view of the spout and cover discharge station taken substantially along the broken line 50—50 in Fig. 18; and
- Fig. 51 is a wiring diagram of the electrical control devices and their circuits.
- The apparatus illustrated in the drawings as an embodiment of the present invention comprises a horizontal turret having a series of spaced can cover receiving pockets, the turret being rotated with an intermittent or step by step movement. During each rest period a formed fibre can cover *a* (shown in detail in Fig. 2) is received in the machine on a cover feeding device and is inserted in a positioned turret pocket at a station A (Fig. 18). This cover has a cylindrical wall *b* which is a bit smaller in diameter than the turret pocket. Upon the next step movement of the turret this cover is brought into a punching or cutting station B. At this station and during the rest period of the turret which follows, the cover being still in the turret pocket, it is subjected to cutting dies which form an opening *c* in the cover *a* which then looks as illustrated in Fig. 3. At the next step rotation of the turret this cover is advanced into a staple forming and inserting station C (Fig. 18). Here the forward end of a wire is presented, the wire being intermittently moved and while at rest its end is cut off in a predetermined length forming a staple blank, the cutting being done at an angle so that the staple blank ends are sharpened. Immediately following both ends of the wire piece or staple blank are bent up into a staple *d*, this action taking place below the cover held in the turret pocket.
- Without any interruption the staple is pushed up and its sharpened ends *e* (Fig. 4) punch through the wall of the cover. The central part of the staple is now located across one end of the cover opening *c*. While cover and staple still remain at this station the staple ends are bent down and the staple is securely fastened in the cover wall as shown in Fig. 5.
- At the next step movement of the turret this staple provided cover is moved from station C into a spout inserting station D (Fig. 18). In the meantime formed metallic pouring spouts *f* (Fig. 6) having flexible side walls or wings *g* have been brought into the apparatus and a spout is positioned in alignment with and directly below the opening *c* of the cover, this relative position of spout and cover being graphically shown in Fig. 6. The spout *f* also has side wing ears *h* projecting outwardly on both sides of a hinge tab *k* extending up from one wall, this wall projecting beyond the side wings *g* in a lift tongue *l*.
- With the cover in the turret pocket at station D instrumentalities operate to partially squeeze the side wings *g* of the spout together and while so held the spout is lifted and its side wings are inserted into the opening *c* of the cover as illustrated in Figs. 7, 8, 9, and 10. This squeezing of the spout walls permits passage of the ears *h* through the cover opening. In Fig. 10 the spout

is fully inserted and its hinge tab *k* is hooked under the central part of the staple. The lift tongue *l* now brought against the under side of the cover prevents it passing further through the cover opening.

During this inserting operation the cover is held down from above and immediately following this assembly of spout and cover and while they are still at the inserting station, other devices operate to partially bend the hinge tab *k* over the staple as shown in Fig. 11. This is sufficient to prevent the spout coming out of the cover as they are next moved by the turret.

Upon the next step rotation of the turret the can cover with its hinged spout is moved from station D into a clinching station E (Fig. 18) where the hinge tab *k* is finally clinched in holding position by being laid down against the spout wall as shown in Fig. 12. This completes the formative operation upon spout and cover. Upon the next step rotation of the turret the cover is moved from station E into a discharge station F and during the following rest period of the turret it is pushed out of the turret pocket and is swept out of the machine.

Connected with the various operating stations are electric control devices which insure proper actions of feeds, forming and assembling movements so that a staple is not formed if there is no cover for it, or a spout is not fed if there is no cover to receive it or if there is not a properly placed staple on which it can be hinged. One control prevents any machine operation if there is not a proper wire supply for making a staple. All of these controls are automatic in their actions as will be fully set forth in the following pages.

The details of the apparatus will be generally considered in the description that follows under a grouping as nearly as can be of the operations which perform the steps just set forth. As nearly as possible all of the mechanism associated with a particular operation will be considered before proceeding to associated mechanisms although there will needs be certain overlapping of parts by reason of their close associations in the unit apparatus.

General characteristics

Substantially all of the working parts of the apparatus are supported on a frame 60 (Figs. 1, 13, and 14) which is formed with vertical, spaced walls 61 terminating at their lower ends in supporting feet 62. Two connecting webs 63 extend across and between the side walls 61 and tie these walls together.

A table 64 is formed with a circular table top 65 which is projected out on opposite sides as at 66, 67 (Fig. 18) and this table is located between 68 and is bolted to the side walls 61. Bolts 71 (Fig. 13) fasten its extension 66 to the left frame wall and bolts 72 (Fig. 14) secure the extension 67 to the opposite side frame.

A spout feeding table 73 (Figs. 1 and 13) is bolted to the table extension 66 and on the opposite side a can cover feed table 74 (Figs. 1 and 14) is bolted at its inner end to the table extension 67 and at its outer end to a bracket 75 which in turn is secured to a side bracket frame 76 extending out from and bolted to the right side frame wall 61.

A turret 81 (Figs. 1 and 18) is located for movement on the table 64 and is provided with a series of spaced can cover receiving pockets 82, there being six of these shown. It is this turret

that presents each of its pockets successively to the various stations of the apparatus as previously briefly described.

Actuation of the operating parts at the various stations A to F, inclusive, is transmitted through mechanism arranged both above and below the turret 81. Movable parts at the various stations which receive actuation from above the turret come indirectly from a crank shaft 91 (Figs. 1 and 17) and the movable parts below the turret as well as the turret itself receive motion by connection with a horizontal cam shaft 92, this shaft receiving its driving power from the crank shaft 91 as will now be briefly set forth.

Shaft 91 is journaled in bearings 93, 94, and 95, the latter being bolted directly to the upper end of one of the side frame walls 61. Bearing 94 is provided by a bracket 97 the lower end of which is bolted to an extension of the upper web 63. Bearing 93 is provided by a bracket 98 which is bolted to the upper end of the opposite side frame 61. The crank shaft 91 is rotated by application of power in any suitable manner as by a belt pulley 99 power driven by a suitable motor not shown in detail but later referred to in a description of the electric controls.

The crank shaft 91 carries a bevel gear 101 which meshes with a similar gear 102 carried on the upper end of a vertical shaft 103 which is journaled in an upper bearing 104 (Figs. 16 and 17) formed in a bracket 105 bolted to the side frame wall 61 and in a lower bearing 106 formed in a bracket 107 also bolted to same side frame.

The lower end of the vertical shaft 103 carries a bevel gear 111 (Figs. 16 and 19) which meshes with a similar gear 112 carried on the lower cam shaft 92. It is by the intermediacy of the shaft 103 that the shaft 92 receives its rotation from the crank shaft 91. The shaft 92 is journaled in bearings 113 formed in the side frames 61 and is further supported in an intermediate bearing 114 carried in a horizontal web 115 connecting the lower parts of the side frames 61.

The cam shaft 92 centrally of the side frame walls carries an interrupted thread spiral gear 117 which operates in connection with a second interrupted thread spiral gear 118 (see also Fig. 1) which is carried on the lower end of a turret shaft 119. The gears 117, 118 are constructed to transform a continuously rotating drive movement of the drive gear 117 to a driven intermittent or step movement transmitted through the gear 118 to the turret 81 which moves one sixth of a revolution and then pauses.

The lower end of the turret shaft 119 is carried in a bearing 121 (Figs. 1 and 19) formed in a bracket which is bolted to the web 115. The upper end of the turret shaft is journaled in a bearing 123 (Figs. 13 and 14) which is formed in the table 64.

It is while a turret pocket 81 is presented for its rest period at station A that a can cover *a* is brought into the pocket from a cover feeding device. This feeding of a cover into the apparatus and the placing of it into the turret pocket 81 at this station will next be described.

Formed cover feed

The can covers *a* are brought into the machine on a conveyor belt 125 (Figs. 14 and 18), the covers being positioned upside down on the belt, that is with their vertical walls *b* extending up. Belt 125 in its machine end operates over a belt pulley 126 which is keyed to a short horizontal shaft 127 journaled in bearings 128 formed in

the cover feed table 74. The shaft 127 is continuously rotated in any suitable manner, one suitable form being illustrated in part as a sheave 129 secured to the shaft for this purpose. A belt 5 or cord drive 131 may be used for driving the sheave.

The can covers are retained in a straight line of travel while carried forward on the belt 125 by being advanced over an auxiliary feed table 10 132 which is secured to the end of the table 74. This brings the covers as far as the feed table 14. The auxiliary table is formed with suitable spaced side walls 133 for guiding the covers in their desired line of travel.

15 The can covers line up on the feed table 74 as the belt 125 forces each cover as far forward as it is free to move and these covers are crowded along and lined up in a row on a runway plate 135 (Figs. 14, 16, and 18) which is mounted upon 20 and secured to the table 74. This plate is formed with a longitudinal channel 136 which provides a guide or runway and along this the row of covers moves.

Cross bars 141 are bolted to and rest on top of 25 the plate 135, these bars being located above the line of travel of the covers. Two parallel guide rods 142 are carried by the cross bars and extend at one end from a position directly over the belt pulley 126 forwardly to a position over a turret 30 pocket at station A. These rods prevent upward displacement of the covers while in the runway 136.

The floor of the plate 135 terminates at a position directly above the turret pocket and provision 35 is made for engaging and advancing each can cover as it comes adjacent the end of the floor and just back of the pocket of the turret. Each cover when it reaches this position is then 40 positively moved forward into alignment with the turret pocket 82 at rest at station A. This advance cover movement will next be considered.

A slide block 145 (Figs. 14 and 16) has longitudinal movement within grooves 146 cut in the upper side walls of the feed table 74 directly below the plate 135 on which the rows of can covers 45 rest. This slide has a forward movement slightly in excess of the diameter of the cover and is sufficient to advance the foremost cover in the row to the turret pocket.

50 The slide 145 is formed with a depending block section 147 and a U-shaped strap 148 is secured to its lower surface. The central part of the strap 148 is in a horizontal plane which is below the edges of the feed table 74 and legs 151 of the 55 U-strap extend up outside of the table. This construction permits free forward and rearward movement of the slide, and the strap 148 without interference with the stationary feed table.

The strap legs 151 also extend forward, as best 60 illustrated in Figs. 14 and 18, and carry a transverse shaft 152 (see also Fig. 16) between their forward ends. This shaft extends across and above the line of travel of the can covers.

A compound lever 161 having a hub 162 is 65 mounted on and pinned to the shaft 152, one end of the lever hub abutting one of the strap legs 151. A similar compound lever 163 having a hub 164 is also mounted on and pinned to the shaft 152, its hub being mounted adjacent the opposite 70 strap leg.

The inner ends of the hubs 162, 164 are spaced a slight distance apart and a slide finger 165 is interposed between the hubs. Arms 166, 167 are formed as integral parts of the respective hubs 75 162, 164 and these extend forward and down and

are connected at their forward ends by a pin 168. Slide finger 165 is mounted on the shaft 152 and on the pin 168 and is formed with a forward cover engaging end 171. Its rear end is slotted at 172, this slot providing a sliding clearance for the 5 shaft 152 and the pin 168. The finger 165 is urged forward and downward in its mounting by a spring device which yields when the end 171 of the finger meets with abnormal resistance during the feeding operation. 10

The lever 161 (Fig. 18) is formed with a rearwardly extending arm 175 which is an integral part of its hub 162 and in a similar manner the lever 163 is provided with an arm 176 which is an integral part of its hub 164. A transverse pin 177 connects the outer ends of the lever arms 175, 176. A roller 178 is rotatably mounted on the pin. 15

It is directly below the roller 178 and located between the lever arms that the spring device for 20 the finger 165 is located. This device comprises a spring barrel 181 (Fig. 14) which slides in a bore 182 formed in a block 183 projecting outwardly from the lever arm 175. A spring 184 is confined within the bore 182 and one end presses 25 against the end of the spring barrel 181 and forces its forward end against the finger 165.

The slide 145 with the finger 165 and the associated parts just described is moved back and forth in regular timed order with the turret 30 movement so that the slide is moved forward and the finger end 171 engages within a can cover a immediately upon beginning of a rest period of the turret. Depending lugs 191 (Figs. 14 and 16) 35 are formed on the rear end of the slide 145 and carry a pin 192 which provides a pivotal mounting for a link 193.

The link 193 is reduced in size at its forward end and extends as a shank 194 which passes 40 through a trunnion 195. A spring 196 is carried on the shank 194 and is held in place by a nut 197. The spring normally urges the trunnion back against the end of the link 193 as illustrated in Fig. 14.

The trunnion 195 is formed with pivotal extensions 198 on which an arm 199 of a bell crank lever 201 engages. Bell crank lever 201 is keyed to a rock shaft 202 which oscillates within bearings 203 formed in the bracket 76. The shaft 202 is shouldered and headed and is held in its rocking position by a nut 204 threadedly engaging one end. A second arm 205 of the bell crank lever 201 extends forward and its end carries a pin 206 on which a roller 207 is rotatably mounted. This roller operates within a groove 208 formed 55 in a barrel cam 209 which is secured to the vertical shaft 103 directly above its bearing 106. 50

The upper surface of the floor of the plate runway 136 at its forward end is inclined at 215 (Fig. 14) and the first of the can covers in the 60 can line as it rests on this inclined part of the runway, is engaged by the forward end 171 of the finger 165 when the latter is rocked as it pauses in its rear position. Rocking of the finger is effected by a rocking of the compound levers 161, 65 163 as the shaft 152 is partially rotated in its mounting in the strap legs 151.

This first of the can covers resting on the inclined floor 215 is yieldingly held in position by a spring finger 216 pivoted at 217 to the feed 70 table plate 135 on one side of the runway 136. A spring pressed barrel 218 presses against this finger so that the cover is held in position until it is positively fed forward as hereinafter described. 75

5 A cam track 221 (Figs. 14 and 16) is formed on the lower surface of a horizontal plate 222 and determines the position of the finger 165 while permitting unrestricted horizontal movement of the slide 145 and the levers carried by it. This plate 222 is carried on a parallel lever device pivoted on stationary parts of the machine.

10 This device includes a rear lever 223 and a front lever 225 both pivotally connected to the horizontal plate. Lever 223 is loosely mounted on a shouldered stud 227 clamped in a boss 228 of a bracket frame 229 (Figs. 1, 14, 15, and 16). The bracket frame 229 is bolted on forward extension blocks 231 extending out from the side 15 walls 61 of the frame.

15 In a similar manner the lever 225 is loosely mounted on a shouldered stud 235 carried in a boss 236 formed in the bracket frame 229. Levers 223, 225 operate as arms of a parallelogram, the 20 distance between the pivotal centers of the upper ends of the levers being equal to that of the lower ends.

25 The lever 223 is a bell crank lever and a laterally extending arm 237 (Figs. 14 and 16) thereof carries a pin 238 on which is rotatably mounted a roller 239. Roller 239 rides on a cam surface 241 of a barrel cam 242 which is mounted upon and rotates with the vertical shaft 103.

30 The roller 239 is normally held down against the cam track 241 by a spring device working against the roller pin 238. This pin is connected with a block 245 carried on the lower end of an adjustable rod 246 which extends up into a sleeve 247 pivotally mounted on the stationary bracket 35 frame 229. For this purpose the sleeve 247 is threadedly secured to a shouldered bolt 248 which is loosely mounted in a boss 249 of the bracket frame.

35 The rod 246 is provided with a head 251 which is located in an upper chamber 252 of the sleeve 247 and a spring 253 mounted on the rod is confined within a lower chamber 254. The spring 253 presses against the dividing wall of the chambers at its top end and below against a collar 45 255 pinned on the rod. This construction normally urges the cam roller 239 down, the cam surface 241 limiting such movement.

40 As long as the roller 239 is on the lower level of the cam 242 the plate 222 is in its raised position. The roller 178 of the lever arms 175, 176 rides along the cam surface 221 of the plate 222, the arms 175, 176 (Figs. 16 and 18) of the levers 161, 163 being urged upwardly by a spring 261 located on the end of the lever hub 163. One 45 end of this spring is secured at 262 to the arm 176 and the opposite end is secured at 263 to the strap leg 151. This spring 261 holds the roller 178 against the cam surface 221, the latter limiting the amount of lifting movement. When 50 the cam plate 222 is in the raised position illustrated in Fig. 14 the end 171 of the finger 165 is in its lowered cover engaging position.

55 Considering the timing of the various actions when the slide 145 is in its rear position the roller 178 is on the rear end of the cam plate which is then in its low position, the roller 239 then riding on the high point of the cam 242. This lowered position of the cam plate has depressed the rear ends of the arms 175, 176 through the roller 178 and has raised the forward end 171 of the finger 165. The raised finger at such a time is above and out of engagement with the can covers 60 a in the runway 136.

65 As the slide 145 begins its forward travel the cam 242 moves its low point surface beneath the

roller 239, the levers 223, 225 rocking counterclockwise (Fig. 14) and raising the plate 222. This allows the spring 261 to rock the levers 161, 163 counterclockwise, depressing the forward end 171 of the finger 165.

70 This forward end thereupon engages inside of the cylindrical wall b of the foremost cover and pushes it forward, moving it down the incline end 215 of the chute 136. Continued movement of the finger sweeps the cover into the station A 10 where it is directly above a positioned turret pocket 82.

15 As the slide 145 approaches the forward end of its stroke the front finger end 171 strikes against a stop rod 265 (Figs. 14 and 18) which is carried in a runway extension 266 mounted on the forward end of the auxiliary table 135. The finger end is arrested in its movement but the slide 145 still continues to move forward a short distance for rounding up of the cover.

20 The forward end of the slide 145 is formed with a semicircular pocket 268 (Fig. 18a) and this now presses against the cover and squeezes its opposite sides against the wall of a pocket 269 formed in a thicker middle section 271 of the 25 turret 81. The upper edge of the cover wall also fits a pocket wall 272 (Fig. 18) formed in the block 266. The cover is held in its rounded-up condition as it is moved down into the turret 30 pocket beneath.

25 During the forward feeding of a can cover just described a vertically movable cover supporting head 281 (Fig. 14) is moved upwardly into the turret pocket. This head is carried on the upper end of a vertical shaft 282 which has sliding movement within a bearing 283 formed in the table 64.

30 The lifting of the head 281 moves it out of a pocket 284 formed in the table and its upper surface comes into a position for receiving the 40 cover being flush with the lower surface of the slide 145. The lifting force for the head is applied by a spring 285 which surrounds the rod 282 and is located within a pocket in the bearing 283, the upper end of the spring pressing directly against the hub of the head. The spring action is controlled by a cam in the following manner.

35 The shaft 282 is pivotally connected to the upper end of an adjustable connecting rod 286, the 50 lower end of which is pivotally connected at 287 to the end of a lever 288 (Figs. 14 and 19). This lever is pinned to one end of a rock shaft 289 which is mounted in a bearing 291 formed in one side frame 61. The rock shaft 289 on the opposite side of the bearing carries an arm 292 (see also Fig. 16) which is pivotally connected at 293 to a link 294 in its turn pivotally connected at 295 to the end of a horizontal lever 296. Lever 296 is mounted for slight rocking movement on a 55 stud 297 (Figs. 15 and 19) carried in a bracket 298 bolted to the side frame 61.

60 The lever 296 intermediate its end carries a pin 299 (Fig. 16) on which is rotatably mounted a roller 301 which rides against a cam 302 (see 65 also Fig. 19) which is secured to the cam shaft 92. This roller is held against the surface of the cam and in this way controls the action of the spring 285 beneath the head 281.

65 The cover a as it rests on the head 281 and is held in rounded up form by the slide 145 is directly beneath an inserting head 311 (Figs. 14 and 20) which is secured below and on one end of a cross head 312. This cross head is bolted to the lower end of a square vertical shaft 313 70 75

- which has sliding movement in bearings 314 formed in the bracket frame 229. When the crosshead 312 is lowered the lower end of the head 311 enters inside of the positioned can cover and continuing its lowering action it moves the can cover down into the turret pocket. The supporting head 281 at such time is forced down against the action of the spring 285 and enters its pocket 284.
- 10 The head 311 is slotted at 316 to permit clearance of the finger 165 which is still in its forward position when the head 311 enters the cover. Other vertical slots 317 are also cut in the head to provide clearance for the guide bars 142 which 15 extend in toward the center of the turret as has been fully described.

The shaft 313 is moved up and down by a cam and is pivotally connected to the lower end of an adjustable connecting rod 322 (Figs. 1 and 20 23). This rod is pivotally connected at its upper end to the end of a lever arm 324 (see also Figs. 17 and 21). The arm 324 is secured to a horizontal rock shaft 325 which is journaled in bearings 326, 327 formed on the upper ends of the 25 bracket arms 97, 98.

The rock shaft 325 also carries a bell crank lever 331 which is keyed to one end and this lever has a short arm 332 (Fig. 22) which extends down below the shaft and which carries a pin 30 333 on which a cam roller 334 is rotatably mounted. The roller 334 operates in a cam groove 335 formed in one surface of a face cam 336 which is keyed to the crank shaft 91.

After the can cover *a* has been seated in the 35 turret pocket 82 at station A the turret remains stationary while the inserting head 311 returns into its raised position and moves up away from the cover. The supporting head 281 is held down in the pocket 284 by the action of the cam 302 40 at such a time. The turret 81 is now ready to advance the cover into the next station, the slide 145 in the meantime having moved back. In the backward movement of the slide, the finger 165 is rocked so that its end 171 raises 45 up clear of the edges of the inserted cover and also clears the other covers within the runway 136.

This feeding of a can cover into station A and its insertion into the turret pocket is prevented 50 if there has been a failure of proper feeding of a pouring spout at another part of the machine. This will be thoroughly brought out step by step when the wiring diagram and the electrical control circuits of the apparatus are later considered. 55 At the present time, however, it will be noted how feeding of a cover is mechanically prevented by failure of the finger 165 to engage the cover as it moves forward with the slide 145. The inserting head 311 is lowered in the regular way but there being no cover in position at station A this is a mere idle movement.

The bell crank lever 223 (Figs. 14 and 16) is formed with an arm 341 which extends up in a 65 vertical position. Normally, that is during regular feeding of a can cover, this arm moves back and forth without meeting any interference, its upper end passing below and closely adjacent to the lower end of a vertically disposed rod 342 which is the core of a solenoid 343 associated with the electric control feature previously mentioned. As long as the arm 341 moves freely the cam plate 222 is moved up so that the finger 165 rocks on its mounting and moves its feed end into a cover.

In the event of an interruption to the normal spout feeding, however, this core rod 342 is allowed to drop down into the path of the arm 341 and prevent its movement. This also prevents the cam roller 239 following down the low 5 section of the cam track 241 which leaves the roller as the cam 242 turns with its rotating shaft 103. The arm 237 at such time stays up in raised position, the spring 253 remaining compressed until the completion of the cycle. The 10 cam plate 222 stays down in such an event and the end 171 of the feed arm is held up as it passes back and forth over and free of the covers in the runway 136.

The solenoid 343 of the electric circuit is carried in a bracket 345 which is mounted upon the bracket frame 229. A boss 346 is formed in the bracket 345 and provides a sliding bearing for the solenoid core 342.

Returning again to a consideration of a can 20 cover properly seated in the turret pocket at station A, upon the next step movement of the turret 81, the cover is transferred from station A (Fig. 18) and is brought into station B. The cover fits fairly snug in the turret pocket but a 25 supplemental clamping device is associated with each pocket for more positively holding the cover during the rotation of the turret. This holding device comprises a slide 351 (Figs. 14, 18, and 18a) located in a radial slot 352 which is cut in the 30 body of the turret 81 adjacent each turret pocket. Each slide 351 carries a clamping head or jaw 353 which has slight movement within an enlarged section 354 of its associated radial slot.

Each slide 351 is formed with a limiting slot 355 into which the lower end of a set screw 356 extends. This screw is threadedly engaged in the thick inner section of the turret 81. This slot and set screw construction limits the radial movement of the slide 351, a spring 357 being 40 interposed between the inner end of the slide and the end wall of the slot 352. The spring normally holds the slide in the position illustrated on the left of Fig. 18 so that its jaw 353 is pressed into the turret pocket as shown at a 45 station D where it engages a cover if there is a cover in the pocket.

This holding action of the jaw 353 is nullified in two places. One of these is at station A where the jaw is held back while a cover is located in the turret pocket. Each slide 351 is formed with a transverse slot 361 cut across its inner surface and as the turret moves to bring the associated pocket to the station A this slot 361 rides over the head of a screw 362 and the slide is moved back. This screw is embedded in the top of the table 64 being located along a radial line extending between the centers of the turret and station A (see Fig. 14).

As soon as the turret moves the can cover 60 from station A the slide 351 passes beyond the stationary screw head 362 and the spring 357 of the slide thereupon forces its jaw 353 outwardly and against the wall of the can cover. This holds the can cover in the turret pocket 65 and it is so clamped throughout subsequent turret movements including its pauses at the various stations up to and including station E. As it approaches station F, however, it engages a second positioned screw 363 (Fig. 18) which again draws the slide jaw back to release the cover for discharge from the machine. This will be fully described later in connection with the cover discharge.

Cover piercing to form a spout opening

At station B the cover is first clamped down on the table 64. Provision is also made at this station for detecting the presence of a cover so that in the event that the turret pocket is empty when brought into station B, feeding of wire for making the next staple will be held up until there is a cover for it. This detecting of the presence of a cover is done electrically and will be described in detail in connection with the wiring diagram. The mechanical features of the electrical contacts at station B, however, will be noted.

As the turret 81 comes to rest at station B the cover is located over an insert die block 375 (Figs. 18 and 24). This die block is held in the table 64 and its upper surface is flush with the upper surface of the table. This brings the cover over an electric contact which comprises a pin 378 located in insulating blocks 379, 381, both pin and blocks being located in a vertical bore 382 cut in the table top 65. These insulating blocks insulate the pin 378 electrically from the table and from the frame of the machine.

The cover *a* is clamped in position at station B by a clamping head 385 which is dimensioned to pass easily inside of the vertical cover walls *b* when the clamping head is brought down. The clamping head and its associated parts are electrically connected with the frame of the machine and this head carries a contact pin 386 which extends down below its lower surface when the clamping head is up.

An enlarged head 387 of the contact pin is located within a vertical bore 388 and a spring 389 is also located in the bore. The lower end of the spring engages the head of the pin and its upper end is engaged by a set screw 391 threaded in the clamping head and closing the upper end of the bore 388. This holds the contact pin in the position illustrated in Fig. 24 but as soon as the clamping head lowers into clamping position the lower end of the pin 386 strikes against the cover and is held against further movement.

The fibrous material of the can cover *a* acts as an insulating medium and prevents an electrical connection between the contact members 386, 378. In the event, however, that a cover is not brought into station B the contact pin 386 directly engages the contact pin 378 and an electrical circuit is formed. This is the mechanism of the testing control contacts and their operation previously mentioned.

The upper end of the clamping head 385 projects outwardly in a flange 392 which is located within a recess 393 formed in the lower end of a head block 394 which is secured to a slide block 395 (Figs. 17 and 20) of a press slide 396.

Slide 396 is associated with and is moved by connection with the crank shaft 91. For this purpose the slide is formed with inclined slide walls 397 one of these having sliding movement within a groove 398 formed in the upper web 63, the other inclined wall sliding on a gib 399 bolted on the frame web. Slide 396 is connected with the lower end of a pitman 401 connected to a crank block 402 operating over the crank 403 formed in the crank shaft 91.

The clamping head 385 (Fig. 24) is held within the chamber 393 by a clamping ring 405 secured on the head block 394 by screws 406. The flange 392 of the head 385 rests on the clamping ring when the parts are in raised position. Springs 407 are interposed between the head block 394 and the clamping head 385, the upper and lower

ends of the springs being confined within vertical bores 408 and 409 formed respectively in the head plate and in the clamping head.

The active cutting die member for forming the spout opening *c* in the can cover *a* comprises a punch 415 having an enlarged end 416 which is seated in and bolted to the under surface of the head block 394. The punch 415 extends down into a vertical opening 418 formed in the clamping head 385 and its lower surface is a slight distance above the lower surface of the clamping head when the parts are in the position of Fig. 24.

When the head block 394 descends for the cutting operation, the clamping head 385 first comes to rest within the can cover *a* and as the head block 394 continues its descent the springs 407 yield, the clamping ring 405 moving down over the outer wall of the now stationary clamping head. The punch 415 moves down through its vertical opening 418 until its lower surface engages the wall of the cover and thence, cooperating with the stationary die block 375, cuts through the cover wall and severs a piece 421 from it.

The cut out piece of cover wall is then pushed down into a die opening 422 cut in the die block 375, thus producing the spout opening *c* (Fig. 3). The cut out piece 421 is pushed away from the lower surface of the punch 415 by an ejector pin 423 slidably located in the lower part of the punch, the head of the pin being backed up by a spring 424 located in a vertical bore 425 formed in the punch. The upper end of the spring is held by a set screw 426 which is threadedly secured in the punch and which closes the bore 425.

The piece 421 falls into an opening 427 which is formed in the table 64 and thence into a discharge chute 428 bolted to the under side of the table. This discharge chute leads the cut out piece to any suitable place of deposit.

Following the cutting operation the head block 394 is raised and the springs 407 hold the clamping head 385 in the can cover until the punch 415 has again moved back into its normal position and until the head flange 392 of the clamping head strikes against and is picked up by the clamping ring 405. This holding down of the cover until the punch is again seated provides a proper stripper action. Further continued upward movement then lifts the clamping head 385 from its position within the can cover and the cover now provided with its opening *c* is ready for transfer to the next station C.

To insure that the turret pocket 82 always stops at an exact point in the various stations A to F, inclusive, there is provided a pilot device associated with the press slide 396 and some consideration will be given to this feature at this time. The outer rim portion of the turret is formed with six spaced bosses 431 (Figs. 1, 17, and 18), a boss being located on a radial line midway between adjacent turret pockets 82.

Each boss is cut through with a vertical bore 432 and as the turret comes to rest following each step movement one of these openings 432 comes directly beneath a pilot pin 433 (Fig. 17) carried by and extending down from the press slide head 395. The lower end of the pilot pin is slightly rounded and easily enters into the turret bore each time the press slide moves down. In this manner each turret pocket is always definitely located at an operating station.

Wire feed

The wire for the staple *d* is cut off from the

end of a continuous wire which is intermittently fed into the machine and in addition to this feeding of a proper amount of wire to make each staple provision is made for momentarily stopping the feed if there is no cover for the next staple so that a given supply of wire is presented in proper time and place to provide for the requirements of staples so that each can cover is properly supplied. Provision is also made for stopping the machine and for preventing any operation if the wire breaks. The feeding of the wire will now be considered.

The wire strand, designated by the numeral 441, is introduced into the back of the machine 15 and is brought into station C (Fig. 18). The table 64 extends back and in between the side walls 61 as a projection 442 which is cut away at station C in a space extending over to station B. This provides a clearance chamber 443 20 (Figs. 27, 29, and 40) in which a ratchet feed mechanism for the wire 441 is located.

This wire in coming into the chamber 443 passes through a horizontal channel 444 cut in the table extension 442. The wire feed mechanism is carried in a bracket 445 which is bolted to the under side of the table, being formed with a foot 446 at the back and with front feet 448, 449, these resting directly against the table wall.

The wire after passing through the channel 444 30 (Fig. 27) is further guided in a horizontal channel 455 formed in a guide block 456 which is held by screws 457 on the bracket 445. From the inner end of the block 456 the wire passes across an intervening space and is further guided in a 35 channel 458 formed in a guide block 459 which is also mounted on the bracket 445 being held in place by screws 461.

The channels 455, 458 aligning with the channel 444 guide the wire in a straight line of travel 40 and the wire is engaged for feeding in that part which extends between the spaced ends of the guide blocks 456, 459. This feeding mechanism comprises two grooved discs between which the wire is engaged and by means of which it 45 is advanced.

One of these, a disc 465 (Figs. 29 and 40) is keyed to the upper end of a vertical ratchet shaft 466 which is journaled in a bearing 467 formed in the bracket 445. The other disc (designated by the numeral 471) is mounted on the upper end of a vertical shaft 472 which is journaled in a bearing 473 formed in a slide block 474. The sides of this block are grooved at 475 where they have sliding engagement with 50 tongued walls 476 of the bracket 445.

The discs 465, 471 clamp the wire 441 in their corresponding grooves with a yielding force that provides a proper frictional engagement to effect the advancement of the wire when the discs rotate. The block 474 is backed up by a spring 477 for this purpose, the spring being partially confined within a pocket 478 formed in a spring cap 479 secured by bolts 481 to the bracket 445. The mounting of the block 474 in its grooved slide ways permits the necessary slight movement under the holding action of the spring as will be readily understood.

A cover plate 482 (Figs. 18, 27, and 40) is set 70 into the surface of the table extension 442 and this covers over the discs 465, 471 and forms a top for the chamber 443. Intermittent motion is transmitted to the feed discs 465, 471 by a pawl and ratchet connection mounted on the shaft 466. The shaft 466 is geared to the shaft 472, 75 a gear 485 (Figs. 29 and 40) being keyed to

the shaft 466 and meshing with a gear 486 which is keyed on the other shaft. A nut 487 threadedly secured to the end of the shaft 472 holds the gear 486 in place.

The teeth of the gears 485, 486 are sufficiently deep to permit any slight lateral movement of the block 474 without moving out of mesh so that both discs are uniformly moved or stopped.

The gear 485 is formed with a hub 490 (Figs. 10, 27, 40, and 41) on which a friction brake is mounted. This brake comprises a pair of jaws 491, 492 hinged at one side of the shaft 466 on a stud 493. This stud is threadedly secured at 15 494 in the stationary bearing 467. The jaws of the friction brake are lined with a suitable fibrous friction material 495 which is squeezed against the hub 490 by a spring device best illustrated in Fig. 41.

This device comprises a bolt 496 which is carried in the free end of the jaw 491 and which extends through a clearance opening 497 cut in the free end of the jaw 492. A spring 498 is mounted on the bolt and is held against the jaw 492 by lock nuts 499 so that there is at all times a spring 25 clamping action effective in the jaws 491, 492 as applied to the gear hub 490. This prevents overthrow of the feed discs 465, 471.

A ratchet 501 (Figs. 27, 29, and 40) is keyed to the shaft 466 directly beneath the gear 485 and 30 is formed with a hub 502. The lower end of the hub is engaged by a washer 503 secured to the shouldered end of the shaft by a lock nut 504. A pawl lever formed with a hub 505 is loosely mounted on the ratchet hub 502 being confined 35 between the washer 503 and the ratchet. The pawl lever hub 505 is an integral part of an arm 506 which extends to one side and loosely carries a short vertical shaft 507.

A pawl or dog 508 is pinned to the upper end 40 of the shaft and is in the same horizontal plane as the ratchet 501. The free end of this pawl or dog normally engages a tooth of the ratchet, a spring 509 yieldingly holding the dog against the ratchet teeth. One end of the spring is secured 45 to a post 511 projecting from the inner side of the dog and its opposite end is secured to a post 512. The ratchet hub 505 is also formed with an arm 515 (Figs. 29 and 40) and the spring post 512 is mounted on and extends up from this arm. 50

The arm 515 extends out to the rear of the apparatus and its end is pivotally connected at 516 to an adjustable connecting rod 517 (see also Figs. 17 and 18). The opposite end of rod 517 is loosely mounted on a bolt 518 which is carried 55 from above in a gear 519. The gear 519 (Figs. 16 and 17) is carried on the lower end of a shouldered and headed stub shaft 521 which is loosely mounted in a bearing 522 formed in a bracket 523 secured to one of the side frames 61. A washer 60 524 and a lock nut 525 hold the gear 519 on the shaft 521.

The gear 519 meshes with a horizontal gear 526 mounted on and keyed to the shaft 103 directly above the cam 209. Continual rotation of the 65 shaft 103 through the gears 526, 519 carries the pin 518 in a rotary path of travel and this oscillates the connecting rod 517 back and forth so that the ratchet dog 508 is also moved back and forth.

Owing to the shape of the teeth of the ratchet 501 and the position of the pawl 508, movement of the latter in one direction (clockwise in Fig. 29) moves the ratchet 501 and the shaft 466 and effects a partial rotation of the feeding discs 465, 70 75 76

471. When the pawl 508 moves in the opposite direction the spring 509 yields and permits snapping of the pawl over the teeth of the ratchet 501 without moving the latter.

5 Reference has already been made to an electric control associated with the contact members 386, 378 of the cutting station B (Fig. 24). When these contact members are not separated from one another by a can cover at that station the 10 electric control set up at that time affects the feeding of the wire 441. This electrical operation will be fully described in connection with the wiring diagram but the mechanical elements associated with the wire feeding and affecting 15 the movement of the feed discs 465, 471 will be briefly considered at this time.

The shaft 507 (Figs. 27 and 29) which is carried in the ratchet arm 506 also carries a second pawl or dog 531 which is pinned to the lower end 20 of the shaft. The two dogs 508, 531 therefore move in unison as the shaft is moved. When there is failure of a can cover at station B the wire feed for that cycle is interrupted by the operation of a solenoid 532 which is located below 25 the wire feeding devices just described.

This solenoid is provided with a core 533 which is normally held below and out of the way of the dog 531 as illustrated in Fig. 27. When there is failure of feeding of a cover, however, the solenoid core 533 is raised into the path of travel of the dog 531 and as it strikes against the core in its bodily movement with the arm 506, it is shifted with its shaft 507 and with the upper dog 508 about the shaft center. This carries the end of the upper dog away from and free of the teeth of the ratchet 501. No feeding movement of the discs 465, 471 takes place and the wire remains where it is.

The solenoid 532 is of the same general type as 40 the solenoid 343 used on the cover feeding end of the machine and already described. This solenoid 532 is bolted at 534 (Figs. 17, 27, and 40) on a bracket 535 which is in turn secured to the web 63 of the frame.

45 Before proceeding to a description of the formation of staples from the wire a brief consideration will be given to the mechanical contacts associated with the control that stops the machine if the wire breaks and that requires a wire supply before it can be operated.

The contact device comprises a detector rod 541 (Figs. 27 and 29) which is one element of an electric contact and which is held out of electric closing position by the wire 441. Rod 541 is formed with a groove 542 and as long as the wire is taut as it passes through the groove the rod 541 is held out in a non-contact position. The rod 541 is slidably mounted in a sleeve 543 which is formed with a foot 544 by means of which it is held in fixed position on the table extension 442.

55 Rod 541 is formed with an enlarged central section 546 which has sliding movement within a chamber 547 formed in the sleeve 543. The section 546 is slotted at 548 and the reduced end of a screw 549 threadedly engaged in the sleeve projects into the slot 548 and acts as a feather to prevent turning of the rod so that its groove 542 60 will be properly presented to the wire at all times.

A spring 551 is located in the chamber 547 and surrounds the rod 541 one end abutting the section 546, the other end being confined by a 70 hollow nut 552 threaded in the end of the sleeve.

The spring tends to pull the rod 541 within the sleeve but the rod is held out by the wire 441 as long as it is properly passing into and through the wire feeding mechanism.

The opposite inner end of the rod 541 projects into a sleeve chamber 553 which contains a threaded contact 554 associated with the electric control hereinafter described. This contact is mounted in the sleeve 543 and is insulated from it by a bushing 555. Should the wire break 10 or fail to properly pass into the feeding devices the spring 551 operates to snap the end of the rod 541 back into the chamber 553 and close the contact between the parts 541, 554. Since the sleeve 543 is grounded in the frame of the machine this closes the electric circuit. 15

Staple forming

The wire 441 after passing through the channel 458 of the guide block 459 enters into and passes 20 through a channel 560 (Fig. 35) formed in a sleeve 561 which is clamped in a side wall 562 of a staple forming housing 563 (see also Figs. 27, 29, and 30). The sleeve 561 is shouldered in 25 the wall 562 and is held in place by lock nuts 564 threadedly engaging its end where it protrudes beyond the wall. The upper part of the housing 563 is in the chamber 443 and this housing is secured to the table extension 442. 30 Bolts 565 clamp a horizontal foot 566 of the housing against the under surface of the table.

The upper surface of the housing is flush with the upper surface of the table extension and the turret 81 moves freely above. This housing is 35 also formed with a second side wall 567 (Figs. 27, 34, and 35) which is parallel to and spaced from the side wall 562. These walls enclose a chamber in which the staple forming and inserting mechanism is in part located.

A spacer plate 571 is located in the upper part 40 of the housing between its side walls and is secured by screws 572 to the rear wall. An inner slide 573 is also located within the housing and its rear wall has sliding engagement with the spacer plate. Slide 573 is formed with a tapered 45 front channel 574 leaving side walls 575 the forward edges of which are flush with the front edges of the housing side walls 562, 567.

An outer slide member 576 (Figs. 27, 30, 31, 50 and 34) is inserted in the front of and has vertical movement in the inner slide 573. The side walls 575 of the former are grooved at 577 and tongues 578 are formed along the front and side edges of the outer slide 576. Plates 581 are screwed to 55 the lower front edges of the housing walls and upper plates 583 are similarly secured to the upper front edges. These plates retain the outer slide member in sliding position and through it the inner slide.

The upper end of the slide 576 is inclined at 60 585 (Fig. 30) and a wire clamping block 586 formed with a hooked head 587 is positioned in front and on top of the slide being secured by bolts 588. The upper inner corner of the block 586 is formed with a transverse groove or pocket 589 in which the wire 441 is adapted to rest during the staple cutting and forming operations.

A lever 595 is mounted for rocking movement 65 on a pin 596 held in lugs 597 formed on the front of the housing walls 562, 567. Lever 595 is bent inwardly from its pivotal mounting and extends upwardly within the slide channel 574 as a vertical arm 598. A clamp block 601 is mounted on the upper end of this arm 598 and is secured by a 70 75

bolt 602. The clamp block 601 extends forward in a projection 603 which, in one position and when the wire extends through the pocket 589, overhangs the head 587 of the block and guides 5 the wire as it passes through the groove 589.

A spring barrel 605 has a short sliding movement in a vertical bore 606 formed in the lower part of the inner slide 573 its upper end extending into the channel 574 of the slide. This 10 spring barrel is seated on a spring 607 and is located in the bore, this spring extending inside of the spring barrel, forcing it against the lower end of the lever arm 598. The spring holds the lever (in the position illustrated in Fig. 30) with 15 the clamp blocks 586, 601 together, their co-operation forming the pocket for the wire as just described.

The lever 595 is also formed with an off-set lower vertically extending arm 608 (Figs. 30 20 and 34) and the inner surface of its lower end is cut back or notched at 609. This cut back surface engages the front wall of a projection 611 extending out from a lower slide block 612 (see also Figs. 27 and 28). Block 612 is 25 formed with depending spaced side plates 613 and is located in the lower end of the housing 563. The walls 613 slidably engage the housing walls 562, 567, being held in sliding position by the plates 581.

30 With the parts in the position illustrated in Figs. 27 and 35 the wire 441 is passed through the channel 560 in the sleeve 561 and through the pocket 589 (Fig. 30) formed in the block head 587 and its forward end is moved beyond 35 the side wall of the latter until it is brought into engagement with the inner tapered end 631 (Figs. 27 and 29) of a stop pin 632. Pin 632 is carried in the upper end of the casing wall 567 and is held in place by lock nuts 633. The forward end of the wire is inclined to the same angle as the tapered pin end 631 and this incline in the wire is the result of a sharpening process used on the previous staple piece as will be hereinafter more fully explained.

45 The cutting of a staple piece or blank from the front end of the positioned wire 441 is effected by raising of the inner slide 573. During the cutting action the outer slide 576 remains in the position illustrated in Figs. 30 and 35 wherein the 50 end of the wire is retained in the same plane as the channel 560 of the sleeve 561.

The inner slide 573 in its lifting movement as a first act carries a cutting die into engagement with the wire. During the second part of the 55 lifting which immediately follows the wire blank is cut. In a third part of the raising action of the slide the ends of the wire are bent up at right angles to form the staple. All three elements of the lifting movement of the inner slide follow 60 in rapid succession and the entire cutting and staple forming operations require only a relatively short time and short lifting movement.

To effect this lifting of the slide 573 the block 612 is raised as will now be described. The sides 65 613 of the block 612 are pivotally connected by a pin 635 (Figs. 27 and 30) to the upper end of an adjustable connecting rod 636 (see also Figs. 13 and 19). The lower end of the rod is pivotally connected at 637 to the end of a lever arm 638 70 which is pinned on a horizontal rock shaft 639.

The shaft 639 is journaled at one end in the bracket 298 and at its opposite end in a bracket 641 (see also Fig. 15). Bracket 641 like the bracket 298 is secured to a side frame 61 of the 75 machine. The shaft 639 also carries a lever

arm 642 (Fig. 19) which at its outer end carries a pin 643 rotatably supporting a cam roller 644. The roller 644 operates in a groove formed in one face of a double face cam 645 which is carried by and secured to the shaft 92. This cam groove is of a shape to oscillate the shaft 639 and its lever arm 638 to raise the block 612 first for a wire cutting operation and then for a staple forming and then a staple inserting operation.

The block 612 is spring connected with the inner slide 573 and the latter carries a stud 651 (Figs. 30 to 33, inclusive) which extends down and passes through a vertical bore 652 formed in the block 612. Block and slide are urged apart by a spring 653 which is located on the stud 651 1 the upper end of the spring being seated in a vertical bore 654 in the lower end of the inner slide.

The lower end of the spring is seated in a counter bore 655 formed in the upper surface of the block. Lock nuts 656 threadedly mounted on the lower end of the stud 651 limit the amount of separation between the parts 573, 612 under the sliding action of the spring. When the block 612 begins its upward movement the inner slide 573 2 is also moved up, the spring 653 maintaining the space between these members for a fractional distance of travel which is the first time interval previously referred to for bringing the upper end 3 of the slide into engagement with the wire.

The upper end of one of the slide side walls 575 of the inner slide 573 carries a die insert 661 (Figs. 27, 29, and 35) set into the front face of the wall. It is held in position by screws 662. This die insert is formed with an inclined wall 3 663 which engages a similar inclined wall 664 formed on the inner end of the sleeve 561. These inclined walls slide on one another at all times and as the inner slide 573 is raised in its initial movement it is the upper end of the die insert 4 661 that comes against the wire where it protrudes beyond the channel 560 of the sleeve.

When the upper end of the die 661 engages the wire the inner slide 573 is momentarily arrested in its lifting movement but the block 612 continues to rise as the spring 653 yields and the distance between the upper surface of the block 612 and the lower surface of the inner slide becomes less. At the same time the upper end of a finger 665 (Figs. 30 and 31) is slid in a notch 666 cut 5 in the rear wall of the inner slide and the latter remains stationary held by the resistance of the wire from above until the upper end of the finger 665 strikes against the end wall of the notch.

Finger 665 is pivotally mounted on a pin 667 51 carried in lugs 668 which extend back from the rear wall of the block 612. The lower end of the finger 665 is engaged by a spring barrel 669 (see also Fig. 28) which slides vertically in a bore 671 formed in a boss 672 extending back from the rear wall of the housing 563. This spring barrel is carried on the upper end of a spring 673 which is located within the bore and the spring pressure against the end of the finger holds its upper end within the slot 666.

The rising finger 665 on striking against the inner slide lifts it with the block 612. The die 661 is thus forced upwardly through the wire and its inclined face 663 shears off a length of wire thus providing the staple blank. By reason 70 of the angular cutting both of the blank ends are angular and this provides sharpened ends for the staple subsequently formed from the blank.

This completes the second step in the lifting action and immediately follows the third part of 75

the movement with the slide 573 still rising. The ends of the wire piece or staple blank now begin to bend as illustrated in Fig. 36.

This bending of the staple ends is accomplished 5 on one side by the cutting die 661 and on the opposite side by the side wall 575 of the inner slide. This wall is cut out at 675 to provide clearance so that the slide moves up without striking the end of the pin 632. The die 661 is formed 10 with a vertical slot 677 and the slide wall 575 on the opposite side is formed with a similar slot 678. These slots 677, 678 are brought up to the ends of the staple as these ends begin to bend from the straight position into the angular position of Fig. 36 and as the slide continues its upward movement the staple ends come into a right angled position within the slots and the staple is fully formed.

It will be observed by comparison of Figs. 20 30 and 32, which show the position of the parts for the operations just described, that the inner slide 573, the block 612 and the finger 665 are substantially the only parts which have moved, the lever 595, the outer slide 576 and 25 parts associated therewith having remained in a stationary position. During this movement, however, the spring barrel 605 has been crowded farther into its bore 606 against the action of the spring 607 as the front lower part of the 30 slide 573 approaches closer to the right angle bend in the lever 595. At the same time the projection 611 of the block 612 has moved up within the slot 609 thus closing the space between the upper inclined wall of the slot and 35 an inclined upper wall 681 of the projection.

The finger 665 at such time rocks slightly on its pin 667. This finger is formed with an inclined rear wall 682 which is spring held by the spring barrel 669 in engagement with a 40 roller 683. The roller 683 is rotatably mounted on a pin 684 carried in the side walls 562, 567 of the housing 563.

During the upward movement of the finger with the rising of the block 612 now being considered, and while the finger is still within the 45 notch 666 of the inner slide 573, its inclined surface 682 is forced forwardly by the roller 683. This rocks the finger in a counter-clockwise direction against the action of the spring barrel 669. At the end of the upward movement of 50 the inner slide, this being when the staple forming operations are completed, the finger has moved up and rocked back into the position illustrated in Fig. 32. Its upper end is now just 55 ready to snap out of the notch 666 of the inner slide.

At the same time the space between the upper surface of the block 612 and the lower face of the outer slide 576 has been lessened. These 60 parts are yieldingly associated through a spring device which comprises a stud 686 which is threadedly secured to the lower part of the slide and which extends down through a vertical bore 687 cut through the block 612. A spring 65 688 is located on the lower end of the stud and is held under compression, with its upper end against the lower face of the block 612, by nuts 689. Spring 688 tends to pull down the outer slide 576 and hold it against a shoulder 691 70 formed on the inner face of each plate 581 (see Figs. 32 and 34).

Staple inserting

The formed staple *d* is still in the pocket 589 75 of the block head 587 and its ends *e* are seated

within the slots 677, 678 of the die 661 and the slide wall 575. By the time the staple forming parts have been brought into the position illustrated in Fig. 32 the can cover *a* has been clamped from above and is ready to receive the 5 staple. This clamping of the can cover will first be considered.

As soon as the turret comes to rest with the can cover at station C a staple inserting and clinching head mounted above the turret comes 10 into action. This head comprises a clamp block 701 (Fig. 30) carried by a projection 702 of the press slide head 395 (see also Fig. 17). The clamp block is supported on bolts 703 which are threadedly secured in the upper part of the block 15 and which have sliding movement within the press head. The clamp block is formed with a central opening 704 in which a stem 705 of the press slide head projects.

The clamp block is normally supported directly on the heads of the bolts 703 and is forced down by a spring 707 located in a central depression 708 formed in the clamp block (see also Fig. 39). When the press slide 396 moves down the clamp block 701 passes into the cover 20 positioned in the turret pocket at station C and as the spring 707 yields, the cover is firmly pressed down on the table extension 442.

The clamp block 701 at station C, like the clamping head 385 at station B, is also provided with an electric contact device by means of which an electric current is set up if there is no can cover present at this station. The electric circuit associated with such a contact will be fully described in connection with the 25 wiring diagram but at the present time the physical or mechanical features relating to the contact devices at station C will be considered.

A contact pin 711 (Figs. 30 and 39) is slidably located in a vertical bore 712 formed in the lower part of the clamp block 701. This pin is held within the bore by a threaded washer 713 and is backed up by a spring 714. When the clamp block 701 is in its raised position the contact pin 711 extends below the lower surface of the 30 block as in Fig. 17.

As long as there is a cover at station C it will act as an insulation when the contact pin 711 is brought down on it. Upon engaging the cover the pin is pushed back into the clamp 35 block (Fig. 30) and the normal operations of the machine will proceed. If there is no cover within the turret pocket to act as an insulation the contact pin 711 when brought down will engage the upper end of a fixed contact 40 pin 715 which is held in insulated bushings 716 seated in the ends of an opening 717 formed in the table projection 442. These bushings insulate the contact pin 715 from the frame of the machine. When an electric contact takes 45 place between the pins 711, 715 the electric control circuit functions to interrupt subsequent operations as will be hereinafter fully set forth.

With the cover clamped down on the table extension 442 and during the final lifting of the 50 block 612, the staple is carried up and its sharpened ends (which it will be recalled were cut off at an angle) are pushed through the wall of the cover, the inserting devices moving from the position illustrated in Fig. 32 to that shown 55 in Fig. 33. During the inserting movement of the staple the overhanging extension 603 of the clamp block 601 is slowly moving back or toward the left (Fig. 32) while the lower inclined wall of the overhang holds the staple in the pocket 70 75

589 of the clamp block 587. This inserting action will be more fully analyzed before proceeding further with the description.

Movement of the clamp block 601 is effected by a rocking of the lever 595 on its mounting 596. The inclined surface 681 of the block 612 slides up and along the inclined top wall of the slot 609 and this throws out the arm 608 of the lever rocking it and further depressing the spring barrel 605 so that the lever upper arm 598 with the clamp block 601 is moved back. This is only an initial rocking of the lever 595 but at this time the upper surface of the block 612 is moving into engagement with the lower surface of the outer slide 576.

Both block 612 and slide 576 now move up and the upper corner of the head 587 pushing against the inclined surface of the overhang 603 rocks the lever 595 further on its pivot and its lower end 20 swings free of the block 612. At the same time the inner slide 573 moves from the position of Fig. 32 into that of Fig. 33 but this movement is under the yielding pressure of the spring 653.

The inner slide 573 is stopped against further movement, and while the block 612 is still rising, by engagement of a rear shoulder 721 (Figs. 32 and 33), formed in its lower end, with the upper wall of a slot 722 formed in the inner lower end of the spacer plate 571. This final lifting of the 30 inner slide 573 carries the die 661 and the wall 575 to a position directly under the can cover so that the grooves 577, 578 form continuous guide-ways for the ends of the staple.

The actual insertion of the staple is effected by 35 a lifting of the outer slide 576 which is raised on the last part of the movement of the block 612. When the block 612 reaches its uppermost position as shown in Fig. 33, the finger 665 under the action of the roller 683 has been rocked into the 40 position shown in that figure. A spacing pin 723 extends in back of the upper part of the finger 665, being held in the housing walls 562, 567, and prevents excessive oscillation of the finger.

Staple clinching

As the sharpened ends *e* of the staple *d* pass through and protrude above the wall of the can cover *a* they move between the ends of a pair of spaced fingers 731 (Figs. 30 and 38). Each 50 finger 731 is pivotally mounted on a shouldered stud 732 (see also Fig. 39) which is threadedly secured in the clamp block 701. At the front the block 701 extends out in side walls 733 and forms a chamber 734 which is closed by a front plate 735. 55 The fingers 731 are located in this chamber.

Each finger 731 along the inside and at its lower end is grooved at 736 and it is into these grooves that the ends of the staple enter when they pass up through the can cover wall. The clamp block 60 701 is also formed with a middle tongue 737 which extends into the chamber 734 in between the fingers.

The upper part of each finger 731 constitutes a tapered end 738 and these two ends are tied 65 together by a spring 739 its ends connecting with pins 741 carried in the fingers. This spring tends to pull the upper ends of the fingers closer together. Its action is limited by the fingers striking against the upper side walls of the tongue 737 70 (Fig. 38).

The slide head 395 continues its downward movement after the staple is fully inserted and after the clamp block 701 and fingers 731 are stationary. The spring 707 yields at such a time. 75 During this movement of the slide head a roller

745, which is mounted on a stud 746 threadedly secured in the stem 705 of the head, engages the inclined inner surfaces of the upper finger ends 738 and forcing the ends apart rocks the fingers on their pivotal mountings. This moves the lower ends of the fingers closer together and bends the staple ends *e* in toward each other laying them flat against the upper surface of the can cover wall. This completes the clinching action and cover and staple then appear as illustrated in Fig. 5.

The stapled can cover is released from clamped position when the clamp block 701 is raised with the slide head 395 the cover remaining held within the pocket of the turret 81. The next turret movement carries the cover into the spout inserting station D.

Spout feeding

The pouring spouts *f* are introduced into the 2 spout feeding table 73 by a belt conveyor, the inner or machine portion of which is best indicated in Figs. 1 and 13. This conveyor carries a horizontally disposed belt 751 which in the machine end passes over a grooved belt pulley 752 2 mounted on and keyed to a horizontal shaft 753. The shaft 753 is mounted in bearings 754 formed in an auxiliary table 755 which is bolted to the end of the spout feeding table 73.

The auxiliary table is formed with spaced parallel guide walls 756 between which the upper run of the belt 751 passes. The pouring spouts *f* are positioned in close processional order on the upper run of the belt in any suitable manner and as they pass between the walls 756 and over the pulley 3 752 they leave the belt and slide along a table top 757 formed in the auxiliary table 755. Belt pulley 752 may be constantly rotated with its shaft 753 in any suitable manner as by application of rotating power to a sheave 758, secured to 4 one end of the shaft, a belt drive 759 being used for this purpose.

An electric control device is associated with the feeding of the spouts at this point and in order for the solenoid 343 of the cover feed to 4 permit feeding of the covers, as previously described, it is necessary that certain electric contacts be closed while the spouts are still in the auxiliary table. The electric features pertaining to this control will be hereinafter described 51 in connection with the wiring diagram but at present the mechanical elements of the contacts will be noted.

An insulating block 761 is inserted in the upper part of the spout passageway in the auxiliary 58 table and this block is mounted in fixed position on the walls 756. Block 761 carries two contact plates 762, 763 which extend down into the spout path. The spouts as they are moved forward by the belt 751 pass beneath and engage these contact members.

As long as the supply of spouts is sufficient to hold adjacent spouts closely together so that there is an unbroken metal connection between them, an electric circuit will be completed between the 65 contacts and current will pass through the interposed spout walls. In the event that there is a failure of feeding of the spouts so that there is an intervening space between adjacent spouts the electric current associated with the contact 70 members is broken as will be hereinafter more fully described.

The belt 751 keeps the spouts in close processional order on the table top 757 and slides along under the spouts when not moving them forward. 75

The spouts pass from the auxiliary table top 751 to a horizontal floor 765 of the spout feed table 73 and at such time pass between side walls 766 (see also Fig. 15) formed in the table 73. These walls 766 are formed with inwardly projecting guide rails 767 which retain the spouts in a straight line of travel and at the same time provide support for a feed bar 768 which is substantially T-shape in cross section, its wider head portion 769 moving freely in grooves 771 formed in the side walls of the table. A slotted top plate 772 rests on and is secured to the walls 766 and retains the feed bar against upward displacement.

The feed bar 768 operates to advance the foremost spout in the processional line into station D and at the same time fits sufficiently close in the spouts and between their side walls *g* to hold them in proper feeding position. The lower surface of the feed bar is grooved at 773 (Figs. 13 and 20 15) which provides a passage clearance for the hinge tabs *k* of the spouts.

The inner end of the feed bar 768 is recessed along its under surface at 775 (Figs. 13 and 43) and a feed dog 776 is pivotally mounted in the 25 recess having rocking movement on a pin 777. The forward end of the feed dog 776 engages the hinge tab *k* of the foremost spout when the feed bar moves the spout from the table floor 765. Movement of the feed bar is effected by a cam on the cam shaft 92 in the following manner.

A lug 781 (Figs. 1, 13, and 15) extends up from the rear end of the feed bar and is pivotally connected to an adjustable link 783 which is also pivotally connected to the end of a lever arm 785 secured to a rock shaft 786. The rock shaft is journaled in a bearing 787 formed in a bracket 788 carried on the bracket frame 229 and in a bearing 789 formed in a bracket 791 bolted to the face of one of the frame side walls 61. 40 Rock shaft 786 also carries a lever arm 792 secured to the shaft and pivotally connected to the upper end of a spring sleeve 794. A spring rod 795 projects into the sleeve 794 and carries a collar 796 which slides inside of the sleeve and which engages and confines a spring 797 mounted on the rod and located entirely within the sleeve. A collar 798 is also pinned to the rod 795 outside of and below the end of the sleeve and this limits the action of the spring 797 which holds up the 50 rod.

The lower end of the rod 795 is pivotally connected to the outer end of a lever arm 801 which is secured to a horizontal rock shaft 802. The shaft 802 is journaled in a bearing 803 formed in a bracket 804 which is bolted to the side frame 61. This shaft also carries a lever arm 805 which extends downwardly and carries a pin 806 on which a cam roller 807 is rotatably mounted. The roller 807 operates within a cam groove 808 formed in a 60 barrel cam 809 carried on the cam shaft 92. Normally the oscillation of the shaft 802 imparts a similar movement to the shaft 786 and thence to the feed bar 768, the rod 795 and the sleeve 794 functioning as a unit.

65 Provision is made for interrupting the feeding of spouts into the machine by preventing the forward movement of the feed bar 768. An electric control is utilized at such a time which is associated with the contact members 711, 715 located at the staple inserting station C and when there is a failure of feeding of a cover into that station an electric circuit is set up which affects a solenoid 811 (Figs. 1, 13, and 15) carried on a bracket 812 bolted to the side frame 61. The electric circuit 75 will be fully discussed later and at present only

the mechanical stopping of the feed bar will be considered.

This solenoid 811 is associated with a horizontal slide rod 813 which constitutes the core of the solenoid, this rod extending forward and sliding in a bearing 814 formed in a bracket 815 which is an integral part of the cover plate 772. Normally, the solenoid core rod 813 is drawn in and held out of the way of the lever arm 785 and as long as it is in this withdrawn condition the feed bar 768 is actuated. When the control circuit functions, however, the rod 813 is pushed forward, this being when the feed bar 768 is on the back stroke as illustrated in Fig. 13.

The projected end of the solenoid core now extends in the path of the swinging lever arm 785, and as the latter moves forward it is blocked by the core rod. Not only is the lever arm 785 now held against movement but there is no rocking of the shaft 786 or movement of the parts 792, 794 20 so that as the rod 795 moves down the spring 797 yields and is compressed, permitting the full stroke of the rod 795 without its transmitting any motion to the stationary sleeve 794.

Before the foremost spout is separated from the 25 row of spouts by a feeding stroke of the feed bar 768 the spout must pass by an escapement device located in the inner end of the spout feeding table 73. This escapement comprises a pair of front fingers 821 (Figs. 42, 43, and 44) and a pair of rear fingers 822, both pairs of fingers being arranged on opposite sides of the line of travel of the spouts. As the feed belt 751 crowds the spouts into the machine the line of spouts is stopped by the front fingers. 35

Each finger 822 is mounted above its corresponding finger 821 and the two fingers on each side of the feed bar are pivotally mounted on a shouldered stud 823 carried in the upper end of the side wall 766 of the spout feeding table 73 and in the 40 cover plate 772, being held in position by a nut 824. The side walls of the feed table are recessed at their forward ends to provide chambers 825 in which the fingers are located.

Each finger 821 is formed with an inward projection 826 and a rectangular pin 827 extends down from this part. The inner extremity of each projection 826 is rounded at 828 and when the feed bar 768 is in its rear or non-feeding position each projection extends into a recess 829 50 cut in the side wall of the bar at its forward end. The depending pins 827 extend into the path of travel of the spouts and hold the entire row or line of spouts by engaging the side lugs *h* of the foremost spout (Fig. 44). The lifting tab *l* of 55 one spout in the row extends under the hinge tab *k* of the proceeding spout and this maintains a uniform order.

The fingers 821 are held in this inner position and their projection extremities 828 are held 60 within the recesses 829 by spring barrels 831 which are slidably mounted in horizontal bores 832 formed in the feed table side walls 766. Each spring barrel 831 is backed up by a spring 833 which forces it against the forward end of the finger. A spring 834 is also connected between upwardly extending posts 835 mounted on the fingers and assists the springs 833 in their holding actions.

The upper or rear fingers 822 are shorter than 70 the fingers 821 and these are also provided with inner projections 836. Each projection is formed with a rounded extremity 837 which strikes against the side walls of the forward end of the feed bar 768. When the bar is in its rear posi- 75

tion (Fig. 42) which is the position now under consideration, the forward ends of the fingers 822 are spread apart. Each finger 822 carries a depending rectangular pin 838 which like the pins 821 of the fingers 821 extends down. These pins 838 on the spread fingers 822 are out of the line of travel of the spout lugs *h*.

The rounded ends 837 of the projections 836 are held against the side walls of the feed bar 10 in the same manner as the corresponding ends of the fingers 821 just described. Each finger 822 is backed up by a spring barrel 839 which has sliding movement within a horizontal bore 841 cut in the forward end of the side wall 766. This 15 spring barrel is pushed inwardly by a spring 842 also located within the bore. Fingers 822 also carry upwardly extending posts 843 and the two posts are connected by a spring 844.

When the feed bar 768 moves forward and the 20 foremost spout *f* is advanced with the feed finger 716 pushing against its hinge tab *k*, the position of the fingers 821, 822 is reversed, that is, the front fingers move out and the rear fingers move in. This action carries the pins 821 out of engagement with the spout lugs *h* of the foremost spout and places the pins 838 in the path of the spout lugs of the second spout in the row and as the full line of spouts moves forward, this second spout is immediately stopped by engagement of its 30 lugs *h* with these pins.

This shifting of the fingers 821, 822 is directly effected by the feed bar. The side walls of the feed bar recesses 829 (Fig. 42) curve outwardly so that as the feed bar advances the forward ends 35 of the fingers 821 ride out of the recesses and are forced apart as their rounded projections 828 come against the wide part of the feed bar. The rounded extremities 837 of the rear finger projections 836 which initially rested against the wide 40 part of the feed bar move in under the combined actions of the springs 842, 844 and enter side recesses or slots 845 cut in the side walls back of and above the recesses 829. It will be observed that the recesses 845 are of substantial length and 45 this permits an extended forward movement of the feed bar while holding the rear feed fingers in.

The feed bar 768 moves the forward spout from the end of the feed table and through an opening 846 cut through a wall of the turret table 64, 50 this opening connecting with a chamber 847 formed in the table at station D. The devices which receive the spout at this station and the inserting instrumentalities are located within the chamber 847.

The spout is received in a cage unit which 55 comprises a pair of side wings 851 (Figs. 42, 45, 46, and 48) located on opposite sides of the line of travel of the spout. Each wing 851 extends toward the turret shaft 119 and is hinged on a vertical shouldered stud 852. This stud is held in a boss 853 formed in a bracket 854 which is bolted to the under side of the table 64, a nut 855 holding the stud in fixed position.

Each side wing 851 carries a block or insert 856 60 secured in the free or unhinged end of the wing by screws 857. Each block insert is formed with a lower inclined side wall 858 the two opposed walls providing a pocket for the incoming spout, each wall having about the same angle as the 65 side wings *g* of the spout.

Directly above the lower wall 858 of each insert 70 is a transverse groove 859 in which a side lug *h* of the spout freely passes. When the spout is received in the cage the side wings 851 are held 75 together in their inner or closed positions (Fig.

48). A transverse rod 861 passes through an opening formed in each side wall and its ends project beyond the walls. Lock nuts 862 threadedly secured on each end of the rod 861 hold a pair of springs 863 also located on the ends of the 5 rod, the springs forcing the free ends of the walls inwardly and holding projections 864 of the block inserts 856 in engagement, these projections providing a front wall for the cage spout pocket.

As the spout moves between the block inserts 10 856 it rides over the upper surface of a spout inserting plunger 865 which is slidably mounted in a boss 866 formed in the bracket 854. As the spout comes to rest in between the inclined walls 858 of the blocks the front tab *l* strikes against and is 15 stopped by the wall projections 864, this position being illustrated in Fig. 45.

A cover plate 868 (Figs. 18 and 45) is positioned over the cage unit and provides a floor for the can cover brought into the station D by 20 the moving turret 81. This plate is set in flush with the upper surface of the table 64 and extends over and is connected to the table. The plate 868 is cut out at 869 and this opening exposes the upper end of the pocket formed by the 25 block inserts 856 so that the pouring spout *f*, as it rests on the plunger 865, is in vertical alignment with and located below the opening *c* cut in the cover *a*. The spout is thus in position for insertion within the cover, which operation will 30 now be described.

Spout inserting

Prior to lifting of the spout and inserting it 35 into the cover opening devices are brought down into holding position within the cover. These devices are carried in a clinching head which is moved up and down and which is shown in detail in Figs. 13, 45, and 49. A clamping head 875 is adapted for movement into the positioned can 40 cover at station D and is formed with an enlarged upper end 876 which normally rests upon a clamping ring 877 carried on the lower end of a clinching head 878, bolts 879 being used to hold the ring in position. 45

The head 875 has vertical movement within the clamping ring and springs 881 are located in vertical bores 882 formed in the clinching head, the lower end of the springs being seated in depressions 883 formed in the upper end 876 of 50 the head. These springs normally hold the shouldered part 876 of the head against the clamping ring as illustrated in Fig. 45.

The clinching head 878 is carried by a cross head 885 (Figs. 13, 20, and 45) a bolt 886 being 55 used to hold the parts together. Cross head 885 is secured to the lower end of a square vertical shaft 887 which is substantially the same construction as the shaft 313 for the cross head 312. The shaft 887 has vertical movement within bearings 888 formed in the bracket frame 229.

The upper end of the shaft 887 (Figs. 1 and 22) is pivotally connected to the lower end of an adjustable connecting rod 892 which at its upper end is pivotally connected to the forward end of 65 an arm 894 carried on the lever 331 (see also Fig. 21). Oscillation of the rock shaft 325 thus provides for the vertical movement of the clinching head 878 which when lowered moves the clamping head 875 into the positioned can cover 70 *a* at station D.

The cover *a* and spout *f* are now in the relative position illustrated in Fig. 6, the cover being held down in its seat against the plate 868 and within the turret pocket 82 by the clamping head 75

875. The spout is inserted by a combination lifting of the spout as the plunger 865 is raised and by partial squeezing together of the spout wings *g* which are held at such time within the block inserts 856. Figure 7 shows the squeezing together of the upper ends of the spout wings to allow the lugs *h* to pass into the opening *c* of the can cover.

The clamping head 875 is cut out along one side to form a chamber 901 (Fig. 45) which is directly above the opening *c* in the clamped can cover. The plunger 865 directly below is held within the boss 866 by a plate 902 and is pivotally connected to the upper end of a connecting rod 903 (Figs. 13, 45, and 46). This rod is connected by an adjustable link 904 to the front end of a lever arm 905 (see also Fig. 19). Lever arm 905 is loosely mounted on the shaft 639 between the lever arm 638 and the bearing 641. Arm 905 carries a cam roller 906 which operates in the groove of a face cam 907 secured to the cam shaft 92.

The insert blocks 856 are formed with inclined walls 909 (Figs. 45 and 46) which join with the walls 858. While the side wings 851 of the spout holding cage are still held together the rising plunger 865 lifting the spout carries its side wings *g* against these inclined walls 909 which force the spout wings in at their top ends and while so held insert them into the cover opening *c*. It will be observed by reference to Fig. 46 that the groove 859 is extended upwardly in a grooved section 911 which allows for clearance on each side for the spout lugs *h*.

35 After the spout has thus been partially inserted within the opening the continued upward movement of the plunger forces it farther into inserted position. At this time, however, the side wings 851 hinge out on their pivotal mounting 852 and the insert walls 909 are moved back and away from spout holding position so that the spout wings under their natural spring move out again and engage the adjacent side edges of the cover opening. This spreading of the side wings and the moving apart of the insert blocks 856 is effected by the plunger 865.

40 The upper part of the plunger is relatively narrow as illustrated in Fig. 46 and the side walls of this narrow part merge in inclined walls 912 into the full width of the plunger. Each side wing 851 is formed with depending lugs 913 (Figs. 46 and 47) there being a pair of lugs on each side of the plunger. A pin 914 is carried in each pair of lugs and a roller 915 is rotatably mounted on each pin.

45 When the plunger is in its lower position these rollers barely engage the side walls of the narrow upper end of the plunger and as the latter moves up and effects the partial insertion of the spout just described the inclined walls 912 strike these rollers and upon continued upward movement of the plunger the rollers spread as they pass to the sides of the wider part of the plunger. This action spreads apart the forward ends of the side walls 851 and moves the insert blocks 856 out of engagement with the spout as has just been described. This spreading of the side walls is accompanied by a compression of the two springs 863 on the cage rod 861.

50 As the spout approaches the full upward position of its inserting travel its hinged lug *k* passes behind the staple *d* in the cover, as illustrated in Fig. 9, and as the plunger 865 reaches the upper end of its travel this hinged lug is fully inserted

behind the staple and the spout and cover are positioned as in Fig. 10.

The plunger 865 is cut away in its forward upper end at 916 (Fig. 45) and when it reaches the upper end of its stroke the bottom end of the 5 plunger recess strikes against a shoulder 917 formed in the front plate 902. This limits the plunger's upward movement. That part of the spout which extends above the wall of the cover is now contained within the chamber 901 of the 10 clamping head 875 and while held in this position the first of the clinching operations takes place.

Spout clinching

A clinching finger 921 (Figs. 45 and 49) is 15 pivotally mounted on a stud 922 which is threadedly engaged in the clamping head 875, this finger being located within a slot 923 formed in the head and extending upwardly from the chamber 901, the lower end of the finger being 20 located within the chamber. During the insertion of the spout which has just been described the finger is held in the vertical position (Fig. 45) by a spring barrel 924 which has sliding movement in a horizontal bore 925 formed in the 25 clamping head. A spring 926 located in the spring barrel presses it against the inner lower face of the finger and holds the upper finger section against the inner wall of the slot 923. In this position the finger backs up the cover wall 30 adjacent the staple, a notch 927 cut in the lower end of the finger, providing clearance for the hinge lug *k* of the spout as it moves into its inserted position.

35 While the spout is so held and while the raised plunger 865 supports it from below the clinching head 878 moves down farther and further compresses the springs 881, this action sliding the clamping ring 877 over the clamping head 875.

40 At the same time a roller 928 rotatably mounted on a stud 929 engages the upper and inner edge of the finger 921, which is inclined as shown in Fig. 45, and rocks it on the stud 922 pressing its notched end 927 against the hinge lug of the spout and bending it over the staple into the 45 partially clinched position illustrated in Fig. 11. Stud 929 is threadedly secured in the clinching head and retains the roller within a chamber 931 formed in the head. This constitutes the first or initial clinching of the spout to the staple 50 of the cover and prevents separation of these parts during the next transfer of cover and spout from the inserting station D into a clinching station E (Fig. 18).

55 At station E the cover is brought to rest with the inserted spout directly under a clinching bar die 934 (Figs. 1, 15, and 20). This die is carried on and extends down from the cross head 885 and when the cross head is lowered on its next stroke the lower end of the die strikes 60 against the hinge lug *k* of the spout and presses it into the fully clinched position shown in Fig. 12. This completes the assembling of spout and cover and leaves the two hingedly connected.

Discharge

65 The can cover with its inserted and hinged spout is next advanced from station E to station F (Fig. 18) which is a discharge station. Since passing the station A it will be recalled that the 70 cover has been held in the turret pocket 82 by the clamping jaw 353 (Figs. 18 and 18a) and as the turret pocket comes to rest at station F the groove 361 formed in the slide 351 is engaged by and rides on the screw 363 previously described. 75

This backs up the jaw and releases its hold against the wall of the cover. The cover is then only loosely held in the turret pocket.

This turret pocket at station F is directly above a depression 936 (Fig. 50) formed in the table 64. A pair of spring pressed blocks 937 having inner serrated walls are located within the depression 936 on opposite sides. Pins 938 threadedly secured in the table extend up into slots formed in the lower surface of the blocks. These blocks are held in within the depression by top cover plates 939 set in the table. The blocks are used as strippers as will now be described.

15 The cover as it rests in the turret pocket at station F is directly beneath a discharge plunger 941 (Figs. 1 and 20) which is carried on the forward end of the cross head 312. When the cross head 312 is lowered the plunger moves down 20 into the cover and forces it down into the depression 936 and out of the turret pocket moving it between the opposed serrated walls of the spring pressed blocks 937. These blocks yield sufficiently to allow the cover to enter fully into 25 the depression. This brings the rim of the cover and the spout entirely below the surface of the table 64 so that when the turret moves on its next advance cycle it clears the discharged spout.

The can cover is now directly in front of a 30 discharge pin 942 (Figs. 18 and 50) carried upon an arm 943 mounted on a vertically extending headed stud 944 (see also Figs. 1 and 16). This stud is held in a bearing 945 formed in the table 64.

A rack bar cage 946 is secured to the lower end 35 of the stud and a gear segment 947 is rotatably mounted on the stud directly above the cage and is secured to the hub of the lever arm 943. The segmental rack 947 is engaged by a rack bar 948 which slides within guideways formed 40 in the rack cage 946 and is pivotally connected to an adjustable connecting rod 949 which is pivotally connected to an arm 951 of a bell crank lever (Fig. 19). This bell crank lever is loosely mounted on the shaft 639 and is located 45 between the lever members 638, 642 and has an arm 952 which extends forward. The arm 952 rotatably supports a cam roller 953 which operates within a cam groove 954 formed on the opposite side of the double cam 645 from 50 the groove in which the roller 644 operates.

By means of the described connections the lever arm 943 (Figs. 18 and 50) is moved forward each cycle of the machine and its pin 942 at such times is moved along an arcuate slot 955 formed in the table 64 below the depression 936. This pin engaging the cover sweeps it from its position, carries it along an arcuate passage 956 which is cut in the table top 65 and pushes it into a discharge chute 957 bolted to the table. 60 This completes the operations in the apparatus as far as they are related to producing a hinged spout can cover.

Electric controls

65 The electric controls which have been mentioned from time to time in the foregoing description are graphically indicated in the wiring diagram (Fig. 51) and reference should now be had to that diagram. There is indicated an 70 electric motor 100 which may be of any suitable form, this form being of no importance as far as the present invention is concerned. For present purposes this motor will be considered as the prime moving element for driving the 75 crank shaft 91 through the belt pulley 99.

Motor 100 is preferably connected in a three-phase wire electric system comprising lead wires m, n, o which preferably pass through a suitable service switch 200 and thence into a switch box 300 which contains start and stop buttons 400 and 500. In this wiring diagram these buttons have been spread out for the sake of clearness and are shown outside of the dotted outline of the switch box. A wire p leads from one side of the starting button switch 400 and connects 10 with the wire o, the opposite side of the starting switch being connected by a wire q to an automatic switch having four-contact points r one point of which is joined by a wire s back to the motor 100. 15

An electric magnet 600 is also located in the switch box 300 and includes a movable solenoid core or similar device which is associated with the automatic switch embodying the contact points r. This switch is a spring back or normally open switch. The magnet 600 is joined by a wire t to the two wires m, n and by a wire u to the frame of the machine which is indicated in the wiring diagram as a ground v. The two contact points r which close with the wires m, n, 25 are connected to the motor 100 by wires w and x.

The wire q connects with one side of the stop switch 500 as well as one side of the start switch 400 and the opposite side of the stop switch connects with a wire y. The solenoids 343, 532, and 30 811 are each connected at one side to the wire y and throughout the normal operation of the machine an electric current flows through and energizes the three solenoids by passing to the frame of the machine shown herein as a 35 ground v.

As long as the solenoids are energized the various operating parts of the machine function normally and it is only when a solenoid is de-energized that the operating parts associated 40 with the control cease to operate. There is one exception to this general statement and that relates to the broken wire detector which is not associated with any of the three solenoids but which stops the motor and all of the machine 45 operations when a shunt circuit is set up through the contacts 541, 554. These various electric circuits will be individually considered in connection with the work performed by a control device associated therewith. 50

In starting the motor 100 the service switch 200 is first closed in the lead lines m, n, o and then the start button 400 is depressed. A momentary starting current flows from the line o, wire p, starting switch 400, stopping switch 500 55 which normally remains closed, wire y, through a connecting wire z which joins the wire y with a ground wire zz connected with a ground v. Connecting through the ground v, which is the frame of the machine, the current flows through 60 the wire u and the electro-magnet 600 and wire t back to the lead lines m, n.

This energizes the electro-magnet 600 and closes the automatic switch at contacts r leading the current into the electric motor 100, the 65 current passing through wire o and wire s and through the wires m, n, w, x to excite the fields of the motor and thus cause its rotation. As soon as the automatic switch is closed at the contact points r a holding current is established 70 which follows the same path as the starting current only now it passes along the wire q instead of the wire p.

The starting button switch 400 no longer is included and its immediate release by the oper- 75

ator in no way affects the operation of the motor. As long as the current flows in this manner the motor operates, the electro-magnet 600 remaining energized and holding the automatic 5 switch closed and connecting the lead wires *m*, *n*, *o* with the wires *s*, *w*, *x* leading into the motor.

The first control device utilizes the electric contacts 762, 763 located on the spout feeding end of the machine and the cover feeding sole- 10 noid 343. The core 342 (Fig. 14) of the solenoid is associated with the rocking of the finger 165 so that its end 171 is either held out of feeding contact with a can cover or in engagement for feeding as has been already described.

15 The solenoid core 342 of the cover feed sole- noid is held back and out of the way of the arm 341 as long as the solenoid is energized. Current flows in this circuit to maintain the solenoid energized as long as there is an electric path be- 20 tween the contacts 762, 763 and this path is maintained by an adequate supply of spouts *f* crowding against each other as previously de- scribed.

25 One end of the winding of the solenoid 343 is connected with the wire *y* by a wire *ca* which preferably leads through an equalizing lamp. The prefix *c* in wire designations signifies that it relates to the cover. The other side of the sole- 30 noid winding connects by means of a wire *cb* to the contact 762. The contact 763 is joined by means of a wire *cc* to the ground wire *zz*.

35 The energizing current for the solenoid 343 therefore utilizes the following path between wires *y* and *zz*, that is, wire *ca* and lamp through the winding of the solenoid, wire *cb*, contact 762, the pouring spouts closing the circuit to the contact 763 and wire *cc* to the ground wire *zz*. If there is a failure of a sufficient supply of pouring spouts *f* entering the machine so that the 40 current is broken between the contact 762, 763 then dropping of the solenoid core 342 on the deenergizing of its solenoid 343 blocks the movement of the lever arm 341 and the feed finger 165 is held out of engagement with a can cover.

45 The second electric control in point of operation utilizes the contacts 386, 378 at station B (Fig. 24) and the wire feed solenoid 532 (Fig. 27). In this case the solenoid 532 when energized holds its core 533 out of engagement with 50 the dog 531 so that the dog 508 then normally engages the teeth of the ratchet 501 associated with the feeding of the wire 441.

55 This solenoid is normally energized by a circuit which does not include the wire contacts 386, 378 located at station B but when these contacts are allowed to electrically connect which occurs only when there is no can cover at station B, then an independent shunt circuit is established which offers less resistance than the re- 60 sistance of the solenoid winding and the electric current instead of passing through the solenoid is shunted as will now be described.

65 One end of the winding of solenoid 532 is connected (Fig. 51) to the wire *y* by a wire *wa*, a lamp being also interposed in this wire line. The prefix *w* here signifies that the line relates to the wire (staple) feed. The opposite end of the solenoid winding connects with a wire *wb* which leads an electric current through a sole- 70 noid core *wc* of an open relay solenoid 700 and a contact *wd* connected with a wire *we* which joins the ground wire *zz*. This is the normal current flow through the solenoid 532.

75 In the event that there is no cover at station B when the cutting head descends and the con-

tacts 386, 378 are electrically connected then a momentary current is set up which deenergizes the magnet 532. This momentary circuit sets the relay 700 so that a more permanent circuit which is then established will hold the solenoid 5 deenergized and give time for the movements of the ratchet feed parts after the contacts 386, 378 are separated. One end of the winding of the open relay solenoid 700 is connected by a wire *wg* to the wire *y* and the other end of the winding 10 connects by a wire *wh* to the contact 386. The contact 378 is connected by a wire *wj* to the ground wire *zz*.

The momentary current flowing through the wire *wg*, winding of the solenoid 700, wire *wh*, 15 contacts 386, 378, wire *wj* and ground wire energizes the open relay solenoid and lifts the sole- noid core *wc*, breaking the current through the solenoid 532 at the contact *wd*.

This lifting of the solenoid core *wc* closes a con- 20 tact for the holding circuit referred to and for this purpose the solenoid core is formed with an associated core part *wk* which when lifted closes a contact at *wl* connected to a wire *wm* leading into a switch 961 the other side of which is joined 25 by a wire *wn* to the ground wire *zz*. The upper end of the solenoid core part *wk* is joined to a wire *wo* which joins the wire *wh* leading from one side of the winding of the solenoid 700.

In the holding circuit electric current now 30 flows as before as far as the wire *wh* but instead of passing into the ground wire by way of the contacts 386, 378 the current flows by way of the wire *wo*, solenoid core *wk*, contact *wl*, wire *wm*, switch 961 and wire *wn* back to the ground line. 35 This, it will be observed, still energizes the sole- noid 700 and holds the contact *wd* open so that solenoid 532 remains deenergized.

40 Reference has just been made to a switch 961 and this switch is shown in Figs. 16 and 26. It is carried on a bracket 962 which is secured to the side frame 61. The switch is provided with the usual contacts which are opened and closed by movement of a lever 963 which carries a roller 964. The position of the lever 963 throughout 45 most of the period of one cycle of operation is closed and at such time the roller is spring held away from the bracket 962.

45 A cam 965 is secured to the vertical shaft 103 and the roller 964 at all times engages this cam. 50 As each cycle of operation of the various movable parts on the machine nears completion a high point on the cam 965 presses the roller 943 toward the bracket 962 as illustrated in Fig. 26 and this opens the switch 961. Without this pro- 55 vision there would be nothing to deenergize the solenoid 700 once the holding circuit was estab- lished. By opening the switch 961 at the end of each cycle the parts of the device are set for proper actuation.

60 As soon as the switch 961 is open (Fig. 51) the holding circuit passing through the winding of the solenoid 700 is broken and the solenoid core parts *wk* and *wc* drop and open the contact *wl*. At the same time the contact *wd* in the circuit of 65 the solenoid 532 closes and that solenoid is im- mediately energized, restoring the wire feed de- vices for normal wire feeding operation.

65 A third control relates to the feeding or pre- 70 vention of feeding of a pouring spout into position below the turret pocket at station D and in- cludes the solenoid 811 and the contacts 711, 715 at station C. Like the preceding electric con- trol for the wire feed just described, an electric current normally flows through the windings of 75

the solenoid 811 and energizes it so that its core 813 is held out of the path of travel of the spout feed arm 785.

One end of the winding of the solenoid 811 is joined by a wire *sa* to the wire *y* and a resistance lamp is preferably introduced in this line. The prefix *s* now used signifies that the line refers to a spout feed. The other end of the solenoid winding is joined by a wire *sb* to a movable solenoid core part *sc* of an open relay solenoid 800. The solenoid core *sc* is joined through a contact *sd* to a wire *se* connected to the ground line *zz*. Flowing of current through this path energizes the solenoid 811.

Normal conditions as to the feeding of spouts obtain as long as the contacts 711, 715 are electrically separated by the presence of a can cover at station C. If there is no cover, however, at this station and the contacts are electrically connected as has been already described, a momentary circuit similar to and functioning the same as the circuit previously described in connection with the solenoid 532, is first set up.

For the momentary circuit current flows from the wire *y* through a wire *sg* to one end of the winding of the solenoid 800 the other side of the winding being joined by a wire *sh*, to the contact 711. The contact 715 is joined by a wire *sj* to the ground line *zz*. As soon as the control contacts are closed and current flows through the windings of the solenoid 800 its core part *sc* is lifted and the current flowing through the solenoid 811 is broken at the contact *sd*.

This lifting of the core is simultaneous with the lifting of a second core part *sk* associated with the core part *sc*. The lifting core part *sk* closes a contact *sl* connected with a wire *sm* which passes into a switch 971. The opposite side of this switch is connected by a wire *sn* to the ground line *zz*.

When the contact *sl* is closed the holding circuit is established and current then flows along the wire *sg* through the solenoid 800, wire *sh* and thence by a wire *so* connected to the top part of the solenoid core *sk*, the current flowing through the core, thence through the contact *sl*, wire *sm*, switch 971 and wire *sn* back to the ground wire. This current it will be observed still energizes the solenoid 800 and as long as its core *sc* is held up the contact *sd* is broken and the solenoid 811 remains deenergized.

The switch 971 (Fig. 16) is the same kind of switch and is operated in the same manner as the switch 961 and is also carried on the bracket 962 above. The switch 971 is opened near the end of each cycle by the operation of a cam 975 secured to the shaft 103 so that the holding circuit is interrupted and the solenoid energizing circuit for solenoid 811 is restored.

The contacts 541, 554 (Fig. 29) which are normally held separated by a wire 441 have been fully described and reference should now be had to Fig. 51 for the wiring of an electric shunt circuit which is set up if the wire breaks and allows the spring 551 to close the contacts. Contact 554 is joined to the wire *y* by a wire *ba* and the other contact 541 is joined, by a wire *bb* preferably through a resistance lamp, to one side of a switch 981. The prefix *b* herein used designates a line associated with a broken wire. The opposite side of this switch is joined by a wire *bc* to the wire *t*.

A shunt circuit established by the closing of the contacts 541, 554 (broken wire or absence of wire) provides a short cut path between the

wire *y* and the opposite side of the lead lines by way of the wire *t*. This shunt circuit has less resistance than the resistance set up in the solenoid 600 and the normal solenoid current is diverted momentarily from the solenoid windings 5 whereupon the automatic switch utilizing the contacts *r* snaps open and breaks the current flow passing through the motor 100. The machine thereupon stops and remains stopped until the start switch is again operated. 10

The switch 981 (Fig. 16) is mechanically like the switches 961, 971 and is also mounted on the bracket 962. Switch 981 unlike the other switches is open for the greater part of the operating cycle of the machine and only closes contact at the end of the cycle. A cam 985 also mounted on shaft 103 operates the switch 981. When a wire breaks and the contacts 541, 554 close they remain closed until a new wire is manually inserted. The stopping shunt circuit, 20 just described is not established, however, until the cam 985 comes around to its high point to close the switch 981.

This provision insures stopping of the machine at the same place each time, that is, with 25 the crossheads 312, 385 and the press slide 396 up so that the various heads carried thereby are held away from the work. This feature prevents mutilation of the cover, staple or spout parts under the various stages of formation or 30 assembly.

A shunt circuit is also employed in the manual stopping of the machine by the stop button 500. The flow of current in the wire *y* at such a time is interrupted by the circuit break in the stop button 35 switch and this momentarily cuts off the holding circuit through the solenoid 600. The automatic switch utilizing the contacts *r* snaps open and breaks the current flow passing through the motor 100. The machine, therefore, stops 40 and remains stopped until the start switch is again operated.

It is thought that the invention and many of its attendant advantages will be understood from the foregoing description, and it will be apparent 45 that various changes may be made in the form, construction and arrangement of the parts without departing from the spirit and scope of the invention or sacrificing all of its material advantages, the form hereinbefore described being 50 merely a preferred embodiment thereof.

I claim:

1. An apparatus for producing pouring spout can covers, comprising in combination, devices for holding a formed can cover having an opening therein and having a wire staple secured in the cover wall with its ends on opposite sides of said opening, and instrumentalities for inserting a pouring spout into said cover opening and into hinging position relative to and with said staple, 55 and means for bending a portion of the spout on said staple.

2. An apparatus for producing pouring spout can covers, comprising in combination, devices for holding a formed can cover having an opening therein, means for clinching a wire staple in said cover with its ends on opposite sides of said opening, and instrumentalities for inserting a pouring spout into said cover opening and into hinging position relative to said staple. 65

3. An apparatus for producing pouring spout can covers, comprising in combination, devices for holding a formed can cover having an opening therein, means for clinching a wire staple in said cover with its ends on opposite sides of said 70

- opening, and instrumentalities including squeezing elements for holding together the spring side walls of a pouring spout while inserting it into said cover opening and into hinging position relative 5 to said staple.
4. An apparatus for producing pouring spout can covers, comprising in combination, devices for holding a formed can cover having an opening therein and having a wire staple secured in the 10 cover wall with its ends on opposite sides of said opening, means for squeezing together the spring side walls of a pouring spout, and instrumentalities for inserting said spout into said cover opening while its side walls are held by said squeezing 15 means so the spout is brought into hinging position relative to and with said staple, and means for bending a portion of the spout on said staple.
5. An apparatus for producing pouring spout can covers, comprising in combination, devices 20 for holding a formed can cover having an opening therein and having a wire staple secured in the cover wall with its ends on opposite sides of said opening, devices for feeding a pouring spout into alignment with said cover opening, instrumentalities for inserting said spout into the said 25 opening, and yieldable members for guiding the forward ends of the side walls of said spout through said cover opening during its insertion by said instrumentalities to bring it into hinging 30 position relative to and with said staple, and means for bending a portion of the spout on said staple.
6. An apparatus for producing pouring spout can covers comprising in combination, devices for 35 feeding a formed can cover into a spout inserting station, said cover having an opening therein and also having a wire staple secured to a wall thereof and extending across said cover opening, devices for feeding a pouring spout into alignment with 40 said cover opening while said cover is at said inserting station, and instrumentalities for inserting said aligned spout into the opening of said cover with a part thereof in hinged engagement with that portion of said staple that extends across 45 said opening and thereby combining the spout with the staple in hinged relation thereto.
7. An apparatus for producing pouring spout can covers, comprising in combination, a conveyor 50 for bringing can covers into the machine, devices for successively feeding a formed can cover from said conveyor and for placing it into a spout inserting station, means for forming a spout opening in said cover, means for securing a wire staple to a wall of said cover so as to extend across the 55 cover opening, devices for feeding a pouring spout into alignment with said cover opening while the cover is at said inserting station, instrumentalities for inserting said aligned spout into the opening of said cover with a part thereof in engagement with that portion of said staple that extends across the opening, and means operating 60 when there is failure of a cover for feeding into said station to arrest the action of said inserting instrumentalities.
8. An apparatus for producing pouring spout can covers, comprising in combination, devices 65 for feeding a formed can cover into a spout inserting station, said cover having an opening in its wall and also having a wire staple secured to the wall and extending across the said opening, devices for feeding a pouring spout into alignment with said cover opening while the cover is at said inserting station, instrumentalities for inserting said aligned spout into the opening of said cover 70 with a part thereof in engagement with that portion of the staple that extends across said opening, and clinching means for hingedly securing the engaged part of said spout on said staple so that the spout is hingedly movable in said cover opening.
9. An apparatus for producing pouring spout can covers, comprising in combination, devices for feeding a formed can cover into a spout inserting station, said cover having an opening in its wall and also having a wire staple secured to the wall and extending across the said cover opening, a clinching head at said inserting station for holding said cover, devices for feeding a pouring spout into alignment with said cover opening while the cover is at said inserting station, instrumentalities at said inserting station for inserting said aligned spout into the opening of said cover with a part thereof in engagement with that portion of the staple that extends across said opening, and clinching means carried in said head for initially securing the engaged part of said spout on said staple so that the spout is loosely connected with said cover.
10. An apparatus for producing pouring spout can covers, comprising in combination, devices for feeding a formed can cover into a spout inserting station, said cover having an opening in its wall and also having a wire staple secured to the wall and extending across the said cover opening, a clinching head at said inserting station for holding said cover, devices for feeding a pouring spout into alignment with said cover opening while the cover is at said inserting station, instrumentalities at said inserting station for inserting said aligned spout into the opening of said cover with a part thereof in engagement with that portion of the staple that extends across said opening, and clinching means carried in said head for initially securing the engaged part of said spout on said staple so that the spout is loosely connected with said cover.
11. An apparatus for producing pouring spout can covers, comprising in combination, devices for holding a formed can cover, piercing means for cutting an opening in said held cover, means for clinching a wire staple in said cover and in position extending across said cover opening, and instrumentalities for inserting a formed pouring spout into said cover opening with the spout in hinging position on said staple.
12. An apparatus for producing pouring spout can covers comprising in combination, devices for holding a formed can cover, piercing means for cutting an opening in said held cover, devices for feeding a wire staple to said cover, means for clinching said staple in the cover wall and in position extending across said cover opening, and instrumentalities for inserting a formed pouring spout into said cover opening with the spout in hinging position on said staple.
13. An apparatus for producing pouring spout can covers, comprising in combination, devices for holding a formed can cover having an opening therein, devices for forming a wire staple having sharp pointed ends, a positioning member for forcing said sharpened staple end through the wall of said cover and in a position with its middle part extending across said cover opening, and means for clinching said wire staple in said cover to form a hinge pintle across said opening for a pouring spout.

14. An apparatus for producing pouring spout can covers, comprising in combination, devices for holding a formed can cover, piercing means for cutting an opening in said held cover, devices for forming a wire staple, a positioning member for inserting the staple ends into said cover with its middle part extending across said cover opening, means for clinching said wire staple in said cover, instrumentalities for inserting a formed pouring spout into said cover opening with the spout in hinged position on said staple, and clinching means for hingedly securing said spout on said staple. 5
15. An apparatus for producing pouring spout can covers, comprising in combination, a clamping head for holding a formed can cover, piercing means carried by said head for cutting an opening in said held cover, devices for forming a wire staple, a stapling head for holding the cover, a 10 positioning member associated with said stapling head for inserting the staple ends into said cover with the middle part of the staple extending across said cover opening, means for clinching said wire staple in said cover, means for holding 15 said cover, instrumentalities for inserting a formed pouring spout into the cover opening with the spout in hinged position on said staple, and clinching means for hingedly securing said spout on said staple. 20
16. An apparatus for producing pouring spout can covers, comprising in combination, devices for feeding a formed can cover into the machine, piercing means for cutting an opening in said cover, feeding devices for bringing a wire into the machine, means for cutting a given length of wire therefrom, devices for forming a wire staple from the said cut wire piece, a positioning member for inserting the staple ends in said cover with its middle part extending across said cover opening, 25 and means for hingedly securing a pouring spout on said staple and in said cover opening. 30
17. An apparatus for producing pouring spout can covers, comprising in combination, devices for feeding a formed can cover into the machine, a clamping head for holding said cover, piercing means carried by said head for cutting an opening in said held cover, feeding devices for bringing a wire into the machine, means for cutting a given length of wire therefrom, devices for forming a wire staple from the said cut wire piece, 35 a stapling head for holding said cover, a positioning member associated with said stapling head for inserting the staple ends in said cover with its middle part extending across a cover opening, a clinching head for holding said cover, and means for hingedly securing a pouring spout on said staple and in said cover opening. 40
18. An apparatus for producing pouring spout can covers, comprising in combination, devices for holding a formed can cover having an opening therein, feeding devices for bringing a wire into the machine, shearing means for cutting off a piece of said wire on a slant so that its ends are pointed, forming said wire piece into a wire 45 staple having sharpened ends, a positioning member for forcing the sharpened ends of said staple through said cover wall, and means for securing said staple in said cover so that it extends across said opening and in position for hingedly retaining a pouring spout in said cover opening. 50
19. An apparatus for producing pouring spout can covers, comprising in combination, devices 55 for holding a formed can cover having an opening therein, feeding devices for bringing a wire into the machine, means for cutting off a piece of said wire on a slant so that its ends are pointed, forming said wire piece into a wire staple having sharpened ends, a positioning member for forcing the sharpened ends of said staple through said cover wall, and means for securing said staple in said cover so that it extends across said opening and in position for hingedly retaining a pouring spout in said cover opening. 60
20. An apparatus for producing pouring spout can covers, comprising in combination, devices for holding a formed can cover having an opening therein, means for cutting off a piece of said wire and forming it into a wire staple, a positioning member for incorporating the said staple in said cover and extending across said cover opening, means for hingedly securing the pouring spout on said staple and in said cover opening, and safety means associated with said wire feeding devices for stopping the other operations upon failure of proper wire feeding. 65
21. In an apparatus for applying hinged spouts, for use on containers, means for forming an opening in the material to which the spout is to be applied, means for attaching a hinge-staple to said material and extending across said opening, means for inserting a spout into said opening, and means for bending a portion of the spout around said staple so as to turn on and relative to said staple. 70
22. An apparatus for producing pouring spout can covers, comprising in combination, devices for holding a formed can cover having an opening therein and having a wire staple secured in the cover wall in predetermined relation to said opening, and instrumentalities for inserting a pouring spout into said cover opening and into hinging position relative to and with said staple, and means for bending a portion of the spout on said staple. 75
23. An apparatus for producing pouring spout can covers, comprising in combination, devices for holding a formed can cover having an opening therein, means for clinching a wire staple in said cover in predetermined relation to said opening, and instrumentalities for inserting a pouring spout into said cover opening and into hinging position relative to said staple. 80
24. An apparatus for producing pouring spout can covers, comprising in combination, devices for holding a formed can cover having an opening therein, means for clinching a wire staple in said cover in predetermined relation to said opening, and instrumentalities including squeezing elements for holding together the spring side walls of a pouring spout while inserting it into said cover opening and into hinging position relative to said staple. 85
25. In an apparatus for applying hinged spouts, for use on containers, means for forming an opening in the material to which the spout is to be applied, means for attaching a hinge-staple to said material in predetermined relation to said opening, means for inserting a spout into said opening, and means for bending a portion of the spout around said staple so as to turn on and relative to said staple. 90

JOHN M. HOTHERSALL.
